NAILING MACHINE

Earle V. Patterson, Pittsford, N. Y., and Clarence A. Macy, deceased, late of Rochester, N. Y., by Susan R. Macy, executrix, Rochester, N. Y., assignors to Morgan Machine Company, Inc., Rochester, N. Y., a corporation of New York

Application November 5, 1938, Serial No. 239,164

58 Claims.

(Cl. 1—8.1)

This invention relates in general to nailing machines and more particularly to a nailing machine adapted to make the panels of a packing or shipping case.

5 An object of this invention is the provision of a machine which is flexible and is adapted to make panels having any desired length, width, thickness, or number of cleats, within the maximum capacity of the machine, nailed in any 10 desired position at a single handling of the panel.

Another object of this invention is to provide a novel machine for nailing a plurality of strengthening bars or cleats to a sheet of board material such as ply-board to thereby form a 15 panel for a ply-board box or shipping case for a refrigerator, radio, or other purposes.

Another object of this invention is to provide a machine, which is capable of nailing different lengths of cleats to a sheet or sheets of ply-board 20 to thereby form a panel.

Another object of this invention is to provide a nailing machine for making cleated ply-board panels, which is sufficiently flexible to enable any desired number of cleats of any desired length, 25 within the limits of the machine, to be nailed to a sheet of ply-board.

Another object of this invention is to provide a nailing machine for nailing cleats to a sheet of ply-board, wherein the nails may be driven, 30 either in a straight line, or in a staggered relationship in various cleats of the same panel.

Another object of this invention is the provision of a nailing machine for making cleated panels wherein the number of nails fed to the 35 machine may be automatically varied so as to vary the number of nails driven in accordance with the length of the cleat to be nailed.

Another object of this invention is the provision of a nailing machine having a variable 40 cycle of operation variable in accordance with the number of cleats to be nailed so that any number of cleats may be nailed to the board in any desired position.

Still another object of this invention is the 45 provision of a movable panel stop automatically operable to enable it to be raised during the cycle of operation of the machine wherein a complete panel is formed with a single handling of the panel, to permit the nailing of a central cleat or 50 a cleat spaced from the ends or sides of the ply-board.

This invention further contemplates a nailing 55 machine wherein means are provided for compensating for the decreased deflection of the machine parts caused when a lesser number

than a full complement of nails are driven, to the end that regardless of the number of nails being driven they are always driven with their heads flush with the surface to which they are nailed.

Other objects and advantages of this invention, for example, the construction of the hopper stop, the arrangement of the ply-board and cleat gauges, and the arrangement of the cleat fingers, will be more apparent from the following description, when taken in connection with the 10 accompanying drawings, in which:

Fig. 1 is a front elevation of the machine with the nail chucks, nail chutes, and nail drivers removed for the purpose of more clearly showing the main structural features of the machine; 15

Fig. 2 is a side elevation of the machine viewed from the left of Fig. 1 with the cross-head down in nailing position;

Fig. 3 is a view similar to that of Fig. 2 20 with the cross-head up;

Fig. 4 is a plan view of a panel with the cleats nailed in position, and illustrating a panel which the machine of this invention is adapted to make;

Fig. 5 is a side elevation of the machine viewed from the right of Fig. 1 with the nail hopper locked in its upper inactive position, and with the nail chucks and hammers in staggered relationship; 25

Fig. 6 is a view similar to that of Fig. 5, but showing only a portion thereof, with the outer 30 nail chucks retracted;

Fig. 7 is a horizontal section through the machine, taken substantially on the line 7—7 of Fig. 1 in the direction indicated by the arrows; 35

Fig. 8 is a horizontal, sectional view through the righthand side of the machine taken substantially on the line 8—8 of Fig. 5 in the direction indicated by the arrows;

Fig. 9 is a view from the righthand side of the machine, somewhat similar to Fig. 6, showing 40 the adjustable stops for limiting the movement of one set of nail chucks with respect to the other;

Fig. 10 is a front elevation of the machine, similar to Fig. 1 but on an enlarged scale, showing the lefthand side of the machine with the cross-head up and with the nail chucks, part of the nail chutes, and the nail drivers in position; 45

Fig. 11 is a sectional view taken substantially on the line 11—11 of Fig. 10 in the direction indicated by the arrows, and showing the nail chucks, nail chutes, and nail drivers; 50

Fig. 12 is a view, partly in section, from the lefthand side of the machine, showing in solid lines a cleat finger in inactive position, and in 55

- dotted lines the cleat finger in active position in holding engagement with a narrow cleat, and also showing the panel stop in the up or inactive position;
- 5 Fig. 13 is an enlarged, sectional view of a portion of Fig. 12 showing the auxiliary spring with which two or more of the cleat finger-operating arms may be equipped;
- 10 Fig. 14 is a view similar to Fig. 12, showing a cleat finger engaging a wide cleat with the auxiliary spring in operation and showing the panel stop in its down or active position;
- 15 Fig. 15 is a view taken substantially on the line 15-15 of Fig. 11 and showing the means for enabling adjustment of one set of nail chucks, with respect to the other;
- 20 Fig. 16 is a view, taken substantially on the line 16-16 of Fig. 14 in the direction indicated by the arrows, showing only the righthand side of the machine and showing the selective ratchet and pawl arrangement for operating the panel stop in synchronism with the operations of the machine;
- 25 Fig. 17 is a view taken substantially on the line 17-17 of Fig. 16, in the direction indicated by the arrows, and showing the active ratchet when five or eight cleats are to be nailed to the plywood;
- 30 Fig. 18 is a view similar to that of Fig. 17, showing the panel-stop-operating mechanism set for making a five-cleat panel;
- 35 Fig. 19 is a view similar to that of Fig. 18, taken substantially on the line 19-19 of Fig. 16 in the direction of the arrows, showing the active ratchet for either a six or seven cleat panel and showing the panel-stop-operating mechanism set for making a seven-cleat panel;
- 40 Fig. 20 is a view taken substantially on the line 20-20 of Fig. 17 in the direction indicated by the arrows;
- 45 Fig. 21 is a view looking at the righthand side of Fig. 16 and showing the cams adapted to be set for nailing either five, six, seven or eight cleats to a sheet of plywood;
- 50 Fig. 22 is a top plan view of Fig. 21 and illustrating how the cams are moved from active to inactive position;
- 55 Fig. 23 is a view taken substantially on the line 23-23 of Fig. 22, and showing a cam in its active position;
- 60 Fig. 24 is a perspective view of a nail driver guide and retainer;
- 65 Fig. 25 is an enlarged view of a portion of Fig. 5, showing the gear train for driving the nail feed discs, and showing how the gears may be quickly changed to adapt the machine for different purposes;
- 70 Fig. 26 is a sectional view taken substantially on the line 26-26 of Fig. 25 in the direction indicated by the arrows;
- 75 Fig. 27 is a view, partly diagrammatic, showing the nail feed discs arranged for nailing five cleats to a sheet of plywood;
- 80 Fig. 28 is a view similar to that of Fig. 27, showing the nail feed discs arranged for nailing seven cleats to a sheet of plywood;
- 85 Fig. 29 is a view, taken substantially on the line 29-29 of Fig. 27 in the direction indicated by the arrows, showing the worm and worm-wheel drive for the nail feed discs;
- 90 Fig. 30 is a view showing the nail-feeding worm and worm-wheel drive, and showing the method of adjusting one section of the worm drive with respect to the other;
- 95 Fig. 31 is a view, taken substantially on the line 31-31 of Fig. 30 in the direction indicated by the arrows, showing one half of the coupling for the sectional worm drive;
- 100 Fig. 32 is a view, taken substantially on the line 32-32 of Fig. 30, showing the other half of the coupling;
- 105 Fig. 33 is a view, partly in section, showing the mechanism for disengaging the hopper from its drive;
- 110 Fig. 34 is a sectional view through the hopper 10 actuating rod;
- 115 Fig. 35 is a view from the righthand side of the machine, showing the mechanism for varying the height of the driving plate of the cross-head with the mechanism set for nailing a short 15 cleat to a sheet of ply-board (cross-head up);
- 120 Fig. 36 is a view, taken substantially on the line 36-36 of Fig. 10 in the direction indicated by the arrows, with the machine set for nailing a long cleat;
- 125 Fig. 37 is a view similar to that of Fig. 35, with the mechanism set for nailing a long cleat (cross-head down);
- 130 Fig. 38 is a view, taken substantially on the line 38-38 of Fig. 10 in the direction indicated by the arrows, showing the machine set for nailing a long cleat (cross-head down);
- 135 Fig. 39 is a view, similar to that of Fig. 38, showing the machine set for nailing a short cleat (cross-head down);
- 140 Fig. 40 is a view taken substantially on the line 40-40 of Fig. 38 in the direction indicated by the arrows;
- 145 Fig. 41 is a view taken substantially on the line 41-41 of Fig. 39 in the direction indicated by the arrows;
- 150 Fig. 42 is a vertical sectional view through the table, showing a sheet of ply-board in position for nailing the central cleat of the panel, and with the panel stop in its up, or inactive, position;
- 155 Fig. 43 is a view similar to that of Fig. 42, showing a sheet of ply-board in position for nailing one of the intermediate cleats of a seven-cleat panel with the panel stop in the up, or inactive, position;
- 160 Fig. 44 is an enlarged view of a portion of Fig. 42, showing one of the intermediate panel-positioning stops;
- 165 Fig. 45 is a top plan view of the intermediate stop shown in Fig. 44; and
- 170 Fig. 46 is a view of a panel with seven cleats nailed in position on the lower side thereof.
- The machine of this invention is adapted for the making of board panels such as ply-board 55 panels for use in making shipping cases, packing cases, crate sections and other forms of containers, such as shipping cases for refrigerators, radios, etc. While for purposes of illustration this machine will be described in connection with the making of a panel of ply-board, other materials may be used. Such other materials include chip-board, paper-board or corrugated paper-board. Further, while this machine will be described in connection with the making of cleated panels, certain features of the machine have general application and may be applied to other types of nailing machines. The panels for the containers or packing cases, due to the various sizes of packing cases required by industry, are 60 of various lengths, widths and thicknesses and require for strengthening purposes various numbers and arrangements of cleats depending upon the size and shape of the panels.
- One of the features of this machine is its flex- 75

ability. That is, within the limits of the machine, any number of cleats, or any length or width of cleats, may be nailed to the ply-board by suitably adjusting the machine, as will presently appear. The machine, for example, is adapted to make a panel such as that shown in Fig. 4, wherein five cleats are nailed to the ply-board, indicated by the letter A: a short cleat B adjacent the center of the panel, another short cleat C at the top edge of the panel, a short, but wide, cleat D at the bottom of the panel, and two long cleats E at the side edges of the panel. The machine is also adapted to nail, for example, 6, 7 or 8 cleats to a sheet of ply-board. In Fig. 46 a seven-cleat panel has been illustrated, which, in addition to the cleats B, C, D and E, is provided with intermediate cleats F, one located between the central cleat B and the top cleat C, and the other located between the center cleat B and the bottom cleat D. It will be appreciated as the description progresses that the cleats may be nailed to the panel in any desired arrangement. For example, a sixth cleat could be added to the panel of Fig. 4 extending perhaps from the cleat B to the cleat D centrally of this portion of the panel or in any other desired position.

The sheets of ply-board are placed on a substantially horizontal surface or table, indicated as a whole by the numeral 50, and guided or controlled by suitable guides, abutments or stops as they are slid over the surface of the table, a cleat or strengthening bar, having previously been placed in nailing position beneath the ply-board, as shown, for example, in Figs. 12 and 33. When the ply-board and the cleat to be nailed to the ply-board are in position, a foot treadle 51 or other manually operated device is operated to actuate, by suitable mechanism to be described, a cross-head or driver head, generally indicated by the numeral 52, to actuate suitable nail driving mechanism, shown more clearly in Fig. 11, to nail the cleat to the panel. The nails are automatically fed to the nail driving mechanism each time the cross-head is actuated through suitable nail-feeding mechanism. The nailing machine of this invention is adapted to drive thirty nails simultaneously, or any desired lesser number of nails. However, it will be appreciated that the machine may be arranged to drive a still greater number of nails at the same time, if desired.

The main frame 56 of the machine comprises a pair of base members 57 (Figs. 1 and 12) which are integrally formed with a pair of side stands 58. The side stands 58 are connected by a box-shaped cross-beam 59 bolted to the side stands (Fig. 12) near the bottom thereof, and an L-shaped beam or sill 60 bolted to the side stands as shown near the top thereof. The side stands 58 of the main frame at their outer sides are each provided with a slide or way 62 (Figs. 1, 6, 7 and 8). The ways extend substantially the full height of the side stands.

The main part of the table 50 comprises a cross-beam 63 (Fig. 12). Bolted, as indicated at 53, to each end of the cross-beam 63 in a plate or gib 64 (Figs. 2 and 7). The side edges of gibs are provided with flanges which engage the ways 62 formed integral with the side stands, as shown at 65 (Figs. 6 and 7). Bolted to the gibs 64 of the table is an apron 66, which extends across the front of the machine, as shown in Fig. 1. Bolted to the other side of the cross-beam 63 is an angle bar 67, which extends across the machine. Secured to the angle 67, in any suitable

manner, is a sheet of boiler plate 71 which forms part of the table surface (Fig. 7). Secured to the plate 71 are a pair of rearwardly extending angle bars 68. A pair of brackets 69, T-shaped in cross-section, are suitably secured to the bottom of the plate 71. The brackets are adjustable by nut and bolt assemblies 70, which are secured in bosses formed in the brackets 69. The nut and bolt assemblies rest against the cross-beam 63 (Fig. 12) so that, upon threading out the bolts from their bosses, the brackets 69 may be raised. The top level of the plate 71 is coincident with the top of the cross-beam 63 and the apron 66, so that a continuous level table surface is provided for receiving the work such as the ply-board panel and the cleats or strengthening bars to be nailed thereto.

The entire table 50 is preferably arranged so that it may be raised or lowered by sliding it upward and downward in the ways 62 of the main frame 56 by means of a pair of table support rods 72 (Fig. 1). The upper ends of the support rods 72 are threaded as indicated at 73 (Fig. 12) and the threaded ends are received in a pair of threaded bosses 74 suitably secured to the cross-beam 63. The lower ends of the table support rods 72 are suitably carried by the main frame, as indicated at 75 (Fig. 1), and the lower ends thereof are provided with bevel gears 76. The bevel gears 76 mesh with bevel gears 77 rigidly mounted on a shaft 78. The shaft 78 is suitably journaled, as indicated at 79, and has rigidly mounted thereon a driven bevel gear 80. The bevel gear 80 meshes with a driving bevel gear 81 rigidly secured to the end of a spindle 82. The spindle 82 projects upward and toward the side of the machine, and has mounted on the end thereof a hand-wheel 83. Upon rotation of the hand-wheel 83, the shaft 78 is rotated, and through the bevel gears 76, 77, the table support rods 72 are rotated to thread the table support rods 72 into or out of the bosses 74 to thereby raise or lower the table 50, as desired.

Journaled in the main frame of the machine, as indicated at 90 (Fig. 1), and supported at substantially its center by a bearing 91, is a main shaft 92, from which preferably all of the driven elements of the machine, with the exception of the nail hopper oscillating mechanism, are driven. The main shaft is driven by means of a suitable gear train, shown more clearly in Figs. 1, 2 and 7, adapted to accomplish a speed reduction and enable the use of a high speed motor. Power from any suitable source, such as an electric motor, is applied to a drive shaft 93, which is suitably journaled in an auxiliary side stand 94. On the drive shaft 93 is mounted a driving pinion 95, which meshes with a large gear 96. The large gear 96 is loosely mounted on the main shaft 92, the main shaft being suitably journaled in the auxiliary side stand 94, as indicated at 97. Also loosely mounted on the main shaft 92 but rotatable with the large gear 96, is a gear 98. The gear 98 meshes with a gear 99. The gear 99 is rigidly secured to a shaft 100, journaled in the auxiliary side stand 94 and in a support 101. Rigidly secured to the end of the shaft 100 is a pinion 102, which meshes with a gear 103. The gear 103 is rigidly mounted on a shaft 104, journaled in the support 101, as indicated at 105 (Fig. 7). The other end of the shaft 104 is supported by a bearing 106 and has rigidly secured thereto preferably an eccentric disc 117 which is the operating ele-

ment of a hopper shaking or oscillating mechanism. The particular hopper operating mechanism shown herein is primarily by way of illustration as any suitable means may be employed 5 for agitating the hopper to cause the nails to feed from the hopper.

The eccentric disc 117 has encircling it an eccentric strap 118, to which is secured a hopper-operating rod 119. As shown in Fig. 34, the 10 hopper-operating rod is slidable in a bore formed in an extension 120 of the hopper-operating rod 119. As the hopper-operating rod is oscillated it engages the end of the bore of the extension and causes the extension to partake of the 15 movement of the hopper-oscillating rod. A shaft 121 (Figs. 2, 3 and 5) extends across the rear of the machine and is journaled in rearwardly extending arms 122 of the side stands 58. A crank 123, having one end rigidly secured to 20 the shaft 121, and the other end secured to the extension 120 of the hopper-operating rod, serves to transmit the oscillating motion of the hopper-operating rod to the shaft 121. The shaft 121 has also rigidly secured to it a plurality of links 25 124, preferably three one for each hopper, the outer ends of which are bifurcated to receive pins 125. The pins 125 are mounted in the bifurcated ends of the links 124 and are adapted to pivotally receive links 126. Each of the links 30 126 is pivoted, as shown at 127 (Figs. 2 and 3), to a bracket carried by a hopper 128.

As shown in the drawings, three hoppers are provided, but obviously an additional or lesser 35 number of hoppers may be employed. The hoppers are of well known construction and are not shown in detail herein, as their construction per se constitutes no part of this invention. The hoppers are adapted to receive nails, and their forward portions are provided with a plurality 40 of slots into which the nails slide point downward as the hoppers are oscillated. Each of the hoppers is pivoted to the rearwardly extending ends of a support or head 135, as indicated at 136, and swings from a position shown in Fig. 3, 45 in which position the rear of the hopper is lowest, to a position shown in Fig. 2, in which the rear of the hopper is uppermost. The slots in the hopper are of sufficient width to enable the nails to hang downward through the slots 50 with the heads of the nails carried in the margins of the slots. The head 135 is secured through extensions 137 to the L-shaped beam or sill 60 (Figs. 2, 3 and 11). The heads 135 also carry plates or slats 138 which extend downward on a 55 slant from the hoppers. The slats 138 are also provided with nail slots 139, which register with the nail slots in the bottoms of the hoppers, so that as the hoppers are oscillated, the nails slide downward into the nail slots 139, and depend 60 below the plate 138, as shown in Fig. 29.

One of the important features of this invention, is the provision of means for interrupting or stopping the oscillation of the hoppers without shutting down the machine. Normally, when 65 the machine is started at the start of a work period, the motor and the driving gear train are kept running continuously, the main shaft 92 being operated to perform nailing operations intermittently through a clutch, as will be presently described. Since the gear train, which 70 actuates the hopper-operating rod, is running continuously, under normal conditions of operation, the hoppers are continuously oscillated. At times, the machine operators are interrupted 75 in their work as, for example, if they are wait-

ing for additional sheets of ply-board or additional cleats. It is desirable under these conditions to stop the hoppers without stopping the motor. The desirability of stopping the hoppers, if the nailing operations of the machine 5 are interrupted for any period of time, arises due to the fact that (considering Fig. 5) nails carried by the slats of the hoppers are continuously being fed into the slots 139 formed between the slats. These nails, with the continued oscillation of the hoppers, are moved at an angle to each other. That is, the nails in the slots 139 are moved and at the low position of the hoppers extend at an angle to the nails in the hoppers. If the slots 139 become full, the 15 angular movement of the nails in the slots 139 with respect to the nails in the slots in the hoppers may cause the nails to jam and become bent substantially at the connections or hinge points 138. 20

While an interruption of the oscillation of the hopper might be accomplished by using a clutch in the driving gear train, interruption of the oscillation of the hoppers may be more simply accomplished by the mechanism shown herein. Secured rigidly to the shaft 121 (Fig. 2) is a latch element 140, which oscillates with the shaft 121. Pivoted to a bracket 141, carried by the sill 60, is a second latch element 142 (Fig. 33). A hopper throw-out rod 143 extends forward from the rear 30 of the machine, and is carried by bracket 144. The hopper throw-out rod has on its rearward end a pair of collars 145, which serve as stops for springs 146. A pair of collars 147 are loosely mounted on the hopper throw-out rod 143, and serve to retain between them the upper end of the latch element 142, which is provided with an enlarged aperture 148 for receiving the hopper throw-out rod 143. The forward end of the hopper throw-out rod is provided with a pair of 40 notches 149, selectively receivable in the margins of an aperture formed in the bracket 144. The outer end of the hopper throw-out rod is provided with a handpiece 150, by which the rod may be operated. A spring 151 normally retains the 45 hopper throw-out rod in the desired position.

When the operator desires to interrupt the oscillation of the hopper, he pulls the hopper-throw-out rod 143 from the position shown in Fig. 33 to its outermost position, thereby compressing the rearward spring 146 and moving the latch element 142 in a clockwise direction, as viewed in Fig. 33. In this position, as shown in Fig. 5, the latch element 142 is in the path of movement of the latch element 140, so that the 55 next time the latch element 140 moves to its uppermost position, during the normal oscillation of the hopper, the end of the latch element 140 cams the end of the latch element 142 aside, so that the latch elements may engage as shown 60 in Fig. 5. In this position of the parts the hopper-operating rod 119 may oscillate freely in the bore of the extension 120, engaging the end of the bore only at the extreme end of its oscillation. Thus, while the latch elements 140 and 142 are 65 engaged, the latch element 140 is lifted slightly at each oscillation of the hopper-operating rod, but not to a sufficient extent to release the latch element 140 from the latch element 142.

When the operator desires to restore the normal oscillation of the hopper, he pushes inward on the hopper throw-out rod 143, thereby compressing the forward spring 146 (as viewed in Fig. 33) and thus tending to urge the latch element 142 in a clockwise direction, as viewed in 75

Fig. 5. Upon the next oscillation of the hopper-operating rod, the latch element 140 is lifted slightly, which permits the forward spring 146 to move the latch element 142 in a clockwise direction, as viewed in Fig. 5, and release the latch elements. The operator, by the hopper-throw-out mechanism described, may quickly start or stop the oscillating of the hopper.

The main shaft 92 is connected to the gear train through a clutch, generally indicated by the numeral 159 (Figs. 2, 3 and 7). The clutch per se constitutes no part of the present invention and has not been shown in detail. It is sufficient to state that the clutch is actuated by the foot treadle 51, which connects the gear 96 to the main shaft 92, the operation of the main shaft being automatically interrupted at the end of one complete rotation of the main shaft 92. The foot treadle 51 is mounted on a shaft 160, journalled in the main frame of the machine, and has rigidly secured thereto an adjustable stop 161 (Fig. 2). The stop 161 limits the downward movement of the foot treadle. Also rigidly connected to the shaft 160 is an arm 162, which is normally urged by a spring 163 in a direction toward the clutch. An adjustable stop 164, which engages the auxiliary side stand 94 limits the inward movement of the arm 162. As shown more clearly in Fig. 3, the clutch is provided with an arm 165, which engages the upper end of the arm 162 to disengage the clutch elements and stop rotation of the main shaft. The arrangement is such that upon depressing the treadle 51 the arm 162 is moved out of the path of the arm 165 against the action of the spring 163, so that the clutch elements are engaged and the main shaft is rotated through one complete rotation. Upon release of the foot treadle 51 the arm 162 is restored into the path of movement of the arm 165 so that the clutch elements are automatically disengaged at the end of a rotation of the main shaft. Preferably a brake (not shown) is mounted on the main shaft which may be automatically applied and disconnected.

Mechanism is provided for feeding the nails from the nail slots 139 to the nail chucks, presently to be described. This mechanism is preferably driven from the main shaft 92 which, as shown in Figs. 5 and 8, projects from the right-hand side of the machine. Upon the projecting end of the main shaft 92 is mounted a bevel gear 169, which meshes with a bevel gear 170 rigidly secured to a shaft 171. The shaft 171 extends upward from a point adjacent the bottom of the machine to a point adjacent the top thereof (Fig. 5), where it is journalled in a bearing indicated at 172 (Fig. 25). The bearing 172 is mounted in a bracket 173 (Fig. 1) supported from the sill 60. Mounted on the upper end of the shaft 171 is a bevel gear 174, which meshes with a bevel gear 175. The bevel gear 175 is loosely mounted on a stub shaft 176 (Fig. 1), which is journalled as indicated at 177 in the bracket 173.

The bevel gear 175 may be integrally formed, or otherwise secured, to a gear 178 also mounted on the stub shaft 176. The gear 178 meshes with an idler gear 179, which is loosely mounted on a stub shaft 180. The idler gear 179 meshes with a gear 186 loose on a sleeve 187 (Fig. 26). The gear 186 may be clutched to the sleeve 187 by clutch elements 188, formed respectively on the face of the gear 186 and on a clutch member 189. The clutch member 189 is keyed to the sleeve, as indicated at 190, and is held on the sleeve by a nut and washer 191. Upon backing

off the nut 191, the clutch member 189 may be removed and the gear 186 slipped off the end of the sleeve 187, and replaced with another gear of larger or smaller diameter, adapted to drive the sleeve 187 at a different rate of speed for a purpose to be later described.

To enable the substitution of a larger or smaller diameter gear for the gear 186, the shaft 180, upon which the idler gear 179 is mounted, is carried by a bracket 192. The bracket 192 extends rearward and is pivoted on the shaft 176. The bracket 192 is formed with a tail part 193, which has an arcuately slotted end as indicated at 194, adapted to receive a nut and bolt assembly 195. An arm 196 is rigidly secured to the bracket 193, extends rearward, and is provided with a plurality of apertures 197 for the reception of a hand adjustable pin 198 carried by the tail part 193 of the bracket. The arm 196 also has a rearwardly extending part 204, adapted to receive the bolt of the nut and bolt assembly 195. Upon removing the pin 198 and loosening the nut and bolt assembly 195, the bracket 192 may be swung about its pivot on the shaft 176 to shift the idler gear 179 out of engagement with the gear 186. The gear 186 may then be slipped off the sleeve 187 and replaced by a gear of the desired size. After replacement of the gear 186, the bracket 192 may be swung back into the position shown in Fig. 25 with the idler gear 179 in engagement with the substituted gear 186. The pin 198 may then be replaced in registry with one of the apertures 197 and the nut and bolt assembly 195 tightened so that a rigid drive is provided between the bevel gear 174 and the substituted gear 186.

The sleeve 187 (Fig. 26), as indicated at 205, is pinned to a shaft 206. The shaft 206 has integrally formed therewith a worm 207, which constitutes the driving element for the nail feeding mechanism. The worm shaft 206 is connected by a coupling element, generally indicated by the numeral 208 (Fig. 30), to a second shaft 209, which has a worm 210 integrally formed therewith. The shaft 209 is connected, 45 by a coupling 211 similar to the coupling 208, to a third shaft 212, having a worm integrally formed therewith. As shown in Fig. 1, the worm shafts 206, 209 and 212 are journalled in the supports 135 and extend across the front of the machine near the top thereof, one worm shaft 50 preferably being provided for each of the nail heads. The coupling element 208 (Figs. 30, 31 and 32) comprises a tube 216, which terminates in a disc 217 and a tube 218, which terminates 55 in a disc 219. The tubes 216 and 218 are slipped respectively over the ends of the shaft 209 and 206 and pinned in position to their respective shafts, as indicated at 220. The disc 217 is provided with a plurality of apertures 221, preferably six, and the disc 219 is provided with a plurality of apertures 222, preferably four. A pair of nut and bolt assemblies 223 extend through the apertures in the discs 217 and 219 60 to couple the tubes 216 and 218 and their respective worm shafts together. Upon removing the nut and bolt assemblies 223, the worm shaft 206 may be rotated with respect to the worm shaft 209, and the nut and bolt assemblies 223 65 inserted in a new pair of apertures in the discs 217 and 219. By the arrangement shown, it is possible to advance one worm shaft with respect to the other 30°, or multiples thereof. The purpose of advancing one worm with respect to the other is to enable the proper synchronizing 70 75

of the nail feed discs, presently to be described, with each other.

Each of the worm shafts 206, 209 and 212 drives a plurality of worm gears 228 (Fig. 29). 5 While the worms may be arranged to drive any desired number of worm gears, and while more or less than three worm shafts may be provided, three worm shafts have been shown, each driving ten worm gears. Each of the worm gears 10 228 is fixed by press-fitting on a vertical shaft 229. As will be apparent, thirty shafts, similar to the shaft 229, are provided and these are rotatably mounted in cross parts 230 carried by the heads 135. Each of the worm gears 228 has 15 removably pinned thereto, as indicated at 231 (Fig. 29), a nail feed disc 232. The periphery of each of the nail feed discs is slightly beveled and is provided with a plurality of slots 233 (Figs. 27 and 28). Each of the discs 232 lies 20 in the path of one of the nail slots 139 in the plates 138, and blocks the movement of the nails, indicated by the numeral 234, down the slots. As a nail disc 232 rotates, the slots therein successively come into registry with the end of 25 a nail slot 139 and a nail is picked up in a slot with its head lying on the margins of the slot. As the disc continues to rotate, it carries with it the nail thus picked up and transfers it to a nail spout or chute 235 (Figs. 10 and 11). Each 30 of the plates 138 is provided with a semi-circular cut-out 236 (Figs. 27 and 28), which registers with a nail chute 235. The ends of the nail chutes are slotted (not shown) and a nail carried by a disc moves through the slot into registry with a nail chute. The nail drops or is 35 kicked off the disc (by means not shown) aided by the beveled edge of the disc, and drops into the chute, point foremost.

The lower end of each of the nail chutes has 40 connected thereto, by a detachable bayonet type pin and slot connection 237, a nail tube 238. The upper end of the nail tube 238 is frustro-conical, as indicated at 239, and below the frustro-conical portion is a flexible part 240, which enables the tube to be bent so that it may be 45 directed to the point desired. Moreover, the pin and slot connection 237 is slightly universal in its action, to further increase the adaptability of the nail tube to be connected between two 50 desired points. The lower end of each of the nail tubes is connected into an opening formed in a nail chuck, generally indicated by the numeral 241. It will be appreciated that each of the nail slots 139 cooperates with a nail feed disc 55 232, and each of the nail feed discs delivers its nails to a chute 235, which in turn delivers its nails to a nail tube 238. Each of the nail tubes is connected to a separate nail chuck 241 (Fig. 10), so that the machine is adapted to deliver 60 a nail to each of thirty nail chucks and the machine is capable of driving thirty nails simultaneously. While thirty nail chutes and chucks have been provided, arranged in banks of ten, it will be appreciated that additional banks may 65 be provided, and that an additional or lesser number of nail delivery mechanisms may be provided in each of the banks.

The cross-head which drives the nails carried by the nail chucks is driven preferably from the 70 main shaft 92. On the main shaft 92 are rigidly mounted, one on each side of the machine, two eccentric discs 250 (Fig. 1), which are connected by eccentric straps 251 (Figs. 3 and 7) to pitman 252. Each of the pitmans has connected to its 75 upper end a member 253 (Fig. 10). Each of the

members 253 is provided with a bore adapted to loosely receive a shaft 254. Each of the shafts 254 is carried in a boss 255 formed as part of the cross-head 52. The cross-head 52 has bolted thereto gibs 256 (Figs. 2 and 11), adapted to be 5 slidably received in the ways 62 of the side stands of the main frame. Upon oscillation of the pitman 252, the cross-head may be moved upward and downward in the ways 62. The outer ends of the shafts 254 carry rollers 257, each of which 10 rides in one of a pair of cam grooves 258, formed in driving-head guides 259. The driving-head guides are pivoted on pins 260, carried by the side stands of the main frame. Each of the driving-head guides has formed integrally therewith, 15 a boss 261, having a bore adapted to receive a driving-head rod 262. Each of the rods 262 is rigidly connected to a boss 263, which is rotatably secured to a pin 264, mounted on a driving head- or chuck bracket plate 265. Two driving-head 20 plates are provided, one on each side of the machine, as shown in Fig. 1.

The inner ends of the plates 265 are provided with U-shaped grooves 270, adapted to slide on the ways 62 (Figs. 6 and 8). The plates 265 are 25 held in position on the ways by gibs 271. The gibs 271 are bolted, as indicated at 272, to the side stands 58 of the main frame, and are provided with ends 273, which form slides and guide for the plates 265. When the cross-head 52 is moved 30 downward, due to rotation of the main shaft 92, the rollers 257, operating in the cam grooves 258, cause downward movement of the driving-head plates 265 through the rods 262. Springs 274 are 35 interposed between the bosses 261 and the bosses 263, so that after the nail chucks engage the ply-board, with the cleat to be nailed positioned below the ply-board, the springs 274 may be compressed to clamp the ply-board against the cleat. It will 40 be noted, due to the cam and roller connection between the cross-head and the driving-head plates 265, that relative movement between the cross-head and the plates occurs as the cross-head moves. Actuation of the cross-heads actuates the plates 265, but relative movement between the plates 265 and the cross-heads is permitted so that upon downward movement of the cross-head the plates 265 are moved more rapidly than the cross-head until the nail chucks engage 45 the ply-board, after which the cross-head continues its descent to perform the nailing operation, as will be presently described. 50

The inner faces of each of the plates 265 are provided with a pair of grooves 275 and 276, forming ways for the reception of slidable plates 277 and 278 (Fig. 8). The plates 277 and 278 are 55 bolted respectively, as indicated at 270, to nail chuck carrier bars 280 and 281. The nail chuck bars 280 and 281 are adapted to receive, adjustably secured thereto, the nail chucks 241. As shown in Fig. 11, the nail chucks are grooved, as 60 indicated at 287, to receive the nail chuck bars 280 and 281, and are adjustably held in position by plates 288, which are secured to the chucks by means of screws 289. Upon loosening the screws 289, each of the chucks individually may be loosened from its respective bar, and adjusted along the bar to any desired position. It will be noted 65 that of the thirty nail chucks, fifteen are mounted on the upper bar 280, and fifteen on the lower bar 281. Bars 290 are also provided for stiffening the nail chuck bars 280 and 281, as the nail chuck bars are subjected to considerable stress when the cross-head moves down to actuate the drivers. 70

The nail chucks per se constitute no part of the present invention, and need be but briefly de- 75

scribed, and since each of the nail chucks is the same in construction, a description of one will suffice. As shown in Fig. 11, each of the nail chucks comprises a body, having a tubular part 294 for the reception of a nail tube 238. The tubular part 294 is connected to a nail chuck (not shown), the position of which is indicated by the numeral 295. Nail chucks suitable for use are well known in the art to which this invention applies and need not be particularly described. The parts of the nail chuck are pivoted on a pin 296, and are located in a vertically extending bore 297 formed in the nail chuck. In each of the bores 297 a driver 298 is actuated when the cross-head 52 comes down. The arrangement of the parts is such that the driver 298, while movable in the bore, is never moved out of the bore, so that it is guided therein. A nail delivered to the nail chuck indicated at the numeral 295 is retained thereby until the cross-head moves downward to drive the drivers 298 into engagement with the head of the nail, whereupon the nail chuck releases the nail and permits the driver to hammer the nail into the work.

As previously mentioned and as will be most clear from Fig. 10, when the ends of the nail chucks move downward into engagement with the top of the ply-board A, upon downward movement of the cross-head 52, the springs 274 are compressed prior to actuation of the drivers 298. The springs 274, which are relatively stiff, cause the chucks to exert a considerable pressure on the top of the ply-board, thus bringing the ply-board into intimate engagement with the cleat B, and tending to straighten out the cleat, should the cleat be somewhat warped. It will further be clear that the nails, by moving the nail chucks along their supporting bars, may be spaced as desired.

One of the important features of this invention is the arrangement for preventing overdriving of the nails, when a lesser number of nails than the full capacity of the machine, is driven. Upon reference to Fig. 46, it will be clear that in nailing the long cleats E to the ply-board, that the full complement of nails may be driven into the cleat. The force required to drive the full complement of thirty nails, so that the heads thereof are flush with the top of the ply-board, is greater than that required to drive a lesser number of nails, for example, when the cross-cleats B, C, D or F are to be secured to the ply-board. Since each time the cross-head comes down the force exerted is the same, it has been found that the spring of the machine parts causes this excess force, for example, when only twelve nails are to be driven, to drive the nails substantially through the ply-board. Or viewed in another way the resistance to the downward movement of the cross-head when less than a full complement of nails is being driven is less than when a full complement of nails is being driven. This lesser resistance permits the machine parts to spring and overdrive the nails. This difficulty can be overcome by increasing the rigidity of the machine parts. This method of overcoming the overdriving of the nails requires an enormous increase in the weight of the machine parts, a heavy and ponderous machine, and a great increase in the cost thereof.

It has been found that the spring of the machine parts may be compensated for by decreasing the possible travel of the drivers when a short cleat is to be nailed in position. This com-

pensating arrangement is shown clearly in Figs. 35-41, inclusive. Mounted in the cross-head 52, extending the full width thereof, and projecting from the ends, are a pair of bars 306 and 307. The bars 306 and 307 have flat portions 308, 5 which extend throughout substantially the entire length of the bars, terminating just short of the ends, as indicated at 309 (Fig. 41). The bars 306 and 307 engage a driving plate 310, which extends across the machine, and terminates at 311 (Figs. 10 and 41). One side edge of the driving plate 310 is supported on a shoulder 312, formed in the cross-head, and the other side edge of the driving plate 310 is supported by brackets 313, secured as indicated at 314, to 10 the cross-head. A plurality of the brackets 313 are provided along the cross-head as shown in Fig. 1, and each is provided with a retaining lip 315 for aiding in supporting the drive plate 310.

Each of the drivers 298 is provided with a 20 head 321, which engages the under surface of the driving plate 310. The drivers 298 are supported in a depending position by nail driver supporting plates 322. The construction of the supporting plates 322 is shown more clearly in 25 Fig. 24. Each of the plates is provided with a slot 323, through which the driver extends, and upon the upper margins of which the head of the driver normally rests. Each of the plates is further provided with downwardly extending 30 flanges 324 and outwardly extending flanges 325. The plates 322 are carried by a pair of bars 326, which extend across the front of the machine, and are supported at their ends from the cross-head. The support for the bars comprises end 35 plates 327 secured to the bars, as indicated at 328 (Fig. 36). The end plates 327 are supported from the ends of studs 329 carried, as indicated at 330, by the cross-head. It will be noted that the nail driver supporting plates 322 are loosely 40 carried by the bars 326, so that the plates may be shifted along the bars when the nail chucks 241, together with the drivers 298, are shifted along the bars 280 and 281. It will also be noted that the drivers may be shifted forwardly and 45 rearwardly in the slots 323, should it be desired to stagger the nails, as will be presently described.

It will now be apparent, as shown in Fig. 38, with the bars 306 and 307 moved so that the 50 round portions of the bars engage the driving plate 310, when the cross-head is moved downward, the drivers 298 will drive the nails the full distance for which the machine is set, that is, to the limit determined by the lowermost 55 position of the cross-head. The bars 306 and 307 are set in this position when a full complement of thirty nails is to be driven for the purpose of nailing a long cleat to the sheet of ply-board. When, however, a short cleat is to be 60 driven, so that, for example, twelve nails are to be driven, the bars 306 and 307 are shifted to the position shown in Fig. 39. With the bars in this position, so that the flat portions of the bars engage the driving plate 310, downward movement 65 of the cross-head to its lowermost position would not enable the driving plate to move downward as far, as with the bars in the position shown in Fig. 38, if it were not for the spring of the machine parts. Since, however, the resistance to downward movement of the driving plate is lessened, the spring of the machine carries the drivers down to the same position as if a greater number of nails were being driven. That is, the apparent downward movement of 70 75

- the driving plate with the arrangement shown in Fig. 39 is not as great as the apparent downward movement of the driving plate with the arrangement shown in Fig. 8. However, this is compensated for by the additional spring of the machine parts due to the fact that less resistance to the downward movement of the cross-head is occasioned when twelve nails are being driven than when thirty nails are being driven.
- 10 The amount which the bars 306 and 307 should be flattened should be, under the conditions of operation described herein, about $\frac{1}{2}$ of an inch, so that whether the machine is driving thirty nails or a lesser number, such as twelve, the nails will be driven with the heads thereof flush with the top surface of the ply-board A.
- 15 Means are provided for adjusting the bars from the position shown in Fig. 38 to that shown in Fig. 39. As shown in Figs. 35 and 37, the bars 20 306 and 307 project beyond the cross-head and have rigidly secured to the ends thereof cranks 331, which are pivoted, as indicated at 332, to a push rod 333. The end of the push rod is provided with a hand piece 334. Secured to or 25 integral with the forward crank 331 is a shifter element 335, which is adapted to be engaged by a shifter element 336. The shifter element 336 is journalled on a boss 337 carried by the driving-head plate 265. The shifter element 336 30 has a detent 338 formed integral therewith, which engages the top edge of the driving-head plate 265 and limits the movement thereof in a clockwise direction, as viewed in Fig. 35. The opposite end of the detent 338 is provided with a 35 spring seat 339. A spring 340 is interposed between the spring seat and the top of the driving-head plate 265, so as to urge the shifter element 336 in a clockwise direction, as viewed in Fig. 35, so that the detent 338 normally engages the top 40 of the driving-head plate 265. A similar arrangement to that shown in Figs. 35 and 37, is provided on the opposite side of the machine, so that the bars 306 and 307 may be actuated from either side of the machine.
- 45 As mentioned above, there is a relative movement between the cross-head 52 and the driving-head plate 265, so that when the driving-head plate 265 moves downward to the limit of its lowermost position, the cross-head following 50 after it causes the shifter element 336 to be cammed aside and to move above the shifter element 335, as shown in Fig. 37. When the cross-head again moves upward, due to continued rotation of the main shaft 92, relative movement 55 between the cross-head and the driving-head plate 265 again takes place. The shifter element 336 then moves downward with respect to the shifter element 335, and moves the shifter element 335, together with the cranks 331, and 60 the push rod 333, from the position shown in Fig. 37 to that shown in Fig. 35.
- 65 In the position of the part shown in Fig. 37, the bars 306 and 307 are in the position shown in Fig. 38, in which position the bars are arranged so that the cross-head will drive thirty nails into the work flush therewith. With the parts in the position shown in Fig. 35, the bars 306 and 307 are 70 in the position shown in Fig. 39 for driving a lesser number of nails than a full complement thereof. It will now be appreciated that at each rotation of the main shaft 92, the shifter element 336 will move upward above the level of the shifter element 335, so that if the shifter element 335 is in the position shown in Fig. 37, during the upward movement of the cross-head the parts

will be restored to the position shown in Fig. 35. The machine is, therefore, always set to nail short cleats in position. When, however, it is desired to nail long cleats in position, the operator pushes on the push rod 333, prior to actuation of the main shaft 92 by the foot treadle 51, and the machine is set with the parts in the relationship shown in Figs. 37 and 38, in which position of the parts a full complement of nails may be driven. Thereafter the shifter elements automatically restore 10 the bars to the position for nailing short cleats.

If desired, the automatic arrangement, described above, for normally restoring the parts to the position shown in Fig. 35, that is, in a position for nailing short cleats, may be eliminated. The operator then will push in on the push rod 333 when a long cleat is to be nailed, and pull outward on the rod 333 when a short cleat is to be nailed. The advantage of the arrangement shown is that the operator knows that whenever he is going to 20 nail a long cleat, he must actuate the push rod.

In Figs. 12 and 14 the mechanism has been shown by which the cleats are held while being nailed. This mechanism comprises a cleat stop 346, which extends across the top of the table, is 25 secured thereto in any suitable manner, and presents an abutment against which the side edge of the cleat is placed. Preferably the cleat stop is beveled or inclined on its rear face, as shown, to enable panels with cleats nailed in position on 30 them and lying beyond the cleat stop to be drawn over the cleat stop. The cleat is held against the abutment, as shown in Fig. 12, by cleat fingers 347 and 347'. These cleat fingers extend across the front of the machine, and normally lie below 35 the table surface 348. The apron 66 of the table is provided with a plurality of slots 349, through which the cleat fingers may be extended to engage the cleat, as indicated by the solid and broken lines in Fig. 12. The cleat fingers normally lie in 40 the position shown in Fig. 12 in solid lines, but upon rotation of the main shaft 92, the cleat fingers are brought to the broken line position shown in Fig. 12. Sufficient pressure is exerted on the cleat fingers and they are spaced along the 45 length of the cleat so that when pressure is exerted the cleat is tightly held against the stop 346. Particularly in the case of a long narrow cleat, the pressure is sufficient to straighten out the cleat if it is slightly warped. It will thus be 50 noted that the cleat is pressed from above by the nail chucks and from the side by the cleat fingers, so that it is rigidly held during nailing, straightened by the pressure exerted and may be nailed flush with the edge of the panel.

55 Each of the cleat fingers is pivotally secured, as indicated at 350, to an arm which may be indicated as a whole by the numeral 351. The arms 351 are solid in the case of the cleat fingers 347 and in two parts in the case of the cleat fingers 347' for a purpose later to be described. Each of the arms 351 is keyed, as indicated at 352, to a shaft 353. The shaft 353 extends across the machine beneath the table and is supported by and journalled in brackets 354 (Fig. 1), which 60 depend from the table. Secured to the shaft 353 are a pair of arms 358, which are pivotally secured by suitable pins to a trunnion 359. The trunnion 359 is mounted and slidable on a connecting rod 360. The connecting rod 360 is threaded, as 65 indicated at 361, into a connection 362. The effective length of the connecting rod 360 may be adjusted by screwing it into or out of its connection 362. Mounted on the threaded portion of the connecting rod 360 is a collar 363, which 70

serves as a stop for one end of a pressure spring 384. The other end of the pressure spring 384 butts against the slideable trunnion 359, as shown at 385. On the other side of the trunnion 359 is a buffer spring 386, which is held in position on the rod by a pair of jam nuts 387.

The end of the connection 382 is pivotally connected, as indicated at 370, to a lever 371, which is journalled, as shown at 372 (Fig. 1), on the shaft 160. Intermediate the ends of the lever 371 is a roller 373 mounted on a pin 374 carried by the lever. The roller 373 is operated by a cam disc 375 (Figs. 1 and 12) fixed to the main shaft 92, as indicated at 376. The cam disc is provided with an inner cam surface 377 and an outer cam surface 378 between which the roller 373 lies and is guided.

Upon actuation of the main shaft 92, the cam disc 375 is rotated to actuate the lever 371, the connecting rod 380, arms 358 and 351, to move the cleat fingers 347 and 347' from and to the solid line position shown in Fig. 12 into and out of engagement with the cleats. The arrangement is such that the cleat fingers are brought into engagement with the cleat and upon further rotation of the cam disc 375, the spring 384, which is relatively heavy, is compressed to exert a heavy pressure on the cleat fingers and the cleats. It will be noted that the cam disc 375 is mounted on the main shaft 92, the rotation of which also actuates the cross-head and the nail feed discs. The shape of the cams of the cam disc 375 is such that the movements of the cleat fingers are synchronized with the movements of the cross-head and the nail feed. The fingers are brought into engagement with the cleat so as to push the cleat, for example, the cleat B in Fig. 12, into engagement with the stop 346 just prior to the engagement of the nail chucks with the top surface of the ply-board A. Upon upward movement of the cross-head, further rotation of the cam disc 375 retracts the cleat fingers to the solid line position shown in Fig. 12.

All of the cleat fingers are effective when a long cleat is to be nailed to the ply-board. However, when a short cleat is to be nailed to the ply-board, only the cleat fingers at the lefthand end of the machine engage the cleat. Should the cleat be a wide cleat, as the cleat D shown in Fig. 14, the pressure exerted by the spring 384 might be too heavy. To avoid this, as shown in Figs. 12 and 14, the arms 351, which actuate the cleat fingers 347', are in two parts. These parts (Figs. 12, 13 and 14) comprise an arm 384, which is rigidly secured to the shaft 353, and provided at its end with an opening 385. A second arm 386 is pivoted, as indicated at 387, to the arm 384 and is pivoted at its other end, as shown at 388, to the cleat finger 347'. The lower end of the arm 386 is bifurcated and provided with a seat 389 for a spring 390. The spring is mounted on a rod 391 and the other end of the spring butts against a washer 392 held in place by a nut. The rod 391 extends through the bifurcated arm 386 and through the aperture 385 formed in the end of the arm 384. The end of the rod is headed, as indicated at 393.

When a wide cleat is to be nailed to the ply-board, upon actuation of the cam disc 375, the shaft 353 is rotated and the cleat fingers 347' brought into engagement with the wide cleat D. Further rotation of the cam disc causes rotation of the shaft 353, which permits the arm 386 to move with respect to the arm 384 about the

pivot 387 to thereby compress the spring 388 and exert pressure on the wide cleat. As shown in the drawings (Fig. 1) two cleat fingers 347' having operating arms as above described are provided. The springs 388 are effective only when a wide cleat is in nailing position to prevent excessive pressure on the wide cleats. Under normal conditions pressure is applied by the spring 384.

To avoid the tendency of the cleats to split, it is desirable that the nails be staggered slightly. Particularly in the case of a wide cleat, it is necessary that the nails be staggered so as to secure better holding engagement of the cleat to the ply-board. To enable staggering of the nails, as mentioned above, half of the nail chucks are mounted on the chuck bar 280 and the other half on the chuck bar 281. Both of the chuck bars are adjustable forwardly and rearwardly to place the rows of nails in any desired position. For the purpose of adjusting the chuck bar 280, the plates 277 (Fig. 8), which carry this bar, are slideable in their grooves 275 in the driving-head plates 265. For this purpose the driving-head plates are slotted, as shown at 399 (Figs. 5, 6 and 11). A bolt 400 secured to the plate 277 extends through the slot 399, and at its outer end is provided with an outer washer and nut 401. By loosening the nuts 401 at each side of the machine the plates 277 may be slid in their respective grooves 275 forwardly or rearwardly to adjust the position of the nail chuck bar 280 as desired.

The slideable plates 278 are adjustable in their grooves 276 to adjust the nail chuck bar 281 forwardly or rearwardly. This means comprises pins 402, which extend through the plates 278 and through slots 403 formed in the driving-head plates 265. The pins 402 are threaded on their inner ends and provided with nuts 404. The outer ends of the pins project beyond the driving-head plates and have pivotally secured thereto arms 405. The arms 405 extend rearwardly (Figs. 5, 6 and 8) and at their rearward ends are, by means of pins 406, pivotally secured to 45 crank 407. The cranks 407 on opposite ends of the machine are rigidly secured to a shaft 408, which extends across the back of the machine. The shaft 408 is provided with a hand lever 409 (Fig. 15), by which the supports for the chuck bar 281 may be slid forwardly or rearwardly. 50 The shaft 408 is secured in position to the frame of the machine by means of brackets 410.

Secured to the shaft 408 by means of a pin 416 (Fig. 15) is a collar 417, which is provided with clutch teeth 418 on the opposite sides thereof. The clutch teeth 418 are adapted to cooperate with similar clutch teeth 419 formed on stops 420 and 421. The stops 420 and 421 are loose on the shaft 408 and are adjustably held in position, so that the clutch teeth are in engagement, by means of springs 422. The springs are confined by one of the brackets 410 and a collar 423 pinned to the shaft. Each of the stops 420 and 421 are provided with stop elements 424 and 425 (Fig. 9), which are adapted respectively to engage the lower 426 and upper 427 edges of a fixed stop 428 secured to the frame of the machine. A scale 429, which may be graduated in inches, is provided on the driving-head plate 265 for the purpose of ascertaining the position of the chuck bar 281 forwardly of its normal position.

By manually pushing either the stop 420 or the stop 421 along the shaft, the clutching en- 75

gagement of the stops to the collar 417 may be released. The stops may then be rotated to an adjusted position to adjust the limits of the movement of the chuck bar 281. As shown in Fig. 9 the stop element 424 on the stop 421 limits the rearward movement of the chuck bar 281, while the stop element 428 on the stop 420 limits the forward movement of the chuck bar 281. It will be readily appreciated that by properly adjusting the stops, any desired staggering of the chuck bar 281, with respect to the chuck bar 280 and thereby the staggering of the nails, may be accomplished. For example, the stop 421 may be set so that when the chuck bar 281 is in its rearward position, a slight staggering of the chuck bar 281 with respect to the chuck bar 280 is occasioned. Thus in securing narrow cleats to the ply-board, only a slight staggering of the nails is accomplished. When a wide cleat is to be nailed, by manually pulling on the hand lever 409 with the stop 420 properly positioned, the staggering of the chuck bars may be increased so as to increase the staggering of the nails. After once set for any particular job, the stops 420 and 421 will normally not require any further adjustment, so that it will be merely necessary to operate the hand lever 409 to shift from a slightly staggered relationship to an increased staggered relationship for nailing wide cleats. If desired, by manually setting the stops the rear chucks may be set forward as will be apparent. Another important feature of this invention is the arrangement of guides or stops for the ply-board and the cleats to enable proper positioning of the ply-board and the cleats with respect to each other and with respect to the nail chucks so that the cleats will be nailed to the ply-board in the proper positions. One of these elements is the cleat stop 346, previously described, and another is a panel stop 441, which is movable from the position shown in Fig. 12 to that shown in Fig. 14 in synchronism with the operations of the machine. In the arrangement shown, the cleat should always be in the nailing position against the cleat stop 346, while the ply-board must be in various relations with the cleat, depending upon the cleat to be nailed. For example, in nailing the end cleats D and C, or the side cleats E, the panel stop must be in the down position, with the vertically extending portion or face 442 thereof in the same vertical plane as the vertically extending portion or face 443 of the cleat stop 346 so that the side edge of the cleat, when in nailed position, will be flush with the edge of the ply-board. However, when either the central cleat B or the intermediate cleats F (Fig. 46) are to be nailed in position, the panel stop 441 must be in the raised position so as to permit the sheet of ply-board to be slid beneath the panel stop and rearwardly onto the table. This enables the central cleat B, or the intermediate cleats F, to be positioned in proper relationship with respect to the sheet of ply-board. The raising and lowering of the panel stop 441 although it may be accomplished manually is preferably accomplished automatically in synchronism with the operations of the main shaft 92, and therefore in synchronism with the movements of the cross-head and the feeding of nails to the nail chucks. As shown in Fig. 8, the panel stop extends across the machine above the table substantially from one side to the other and is L-shaped in cross-section (Figs. 12 and 14), having the vertically extending portion 442 and

a horizontally extending portion 443. Secured to the top surface of the horizontally extending portion 443 are a pair of brackets 444, which are apertured to pivotally receive the bent ends 445 of rods 446. The rods 446 extend upward from the brackets and through enlarged apertures 447 formed in the ends of arms 448. The rods 446 are retained in the apertures in the arms by nuts 449. The arms 448 extend rearwardly (Figs. 8 and 12) and are rigidly secured, as shown at 454, to a shaft 450, which extends across the machine, and is journaled in the side stands, as shown at 451 (Fig. 8). For the purpose of guiding the panel stop during the raising and lowering thereof, the cleat stop 346 has projecting above the surface thereof, a pair of pins 454, one at each end of the machine (Figs. 7, 8 and 10). The pins which also extend into the table, as the panel stop is raised and lowered, are slideable in apertures 455 formed in brackets 456 carried by the panel stop.

At the righthand side of the machine, as shown in Fig. 8, the shaft 450 projects beyond the side stand and at its outer end there is pinned an arm 452. On the outer end of the arm 25 is a weight 453, which is adjustable along the arm and which acts against the lowering of the panel stop 441 as will be apparent from Fig. 12. Thus when the panel stop is moved from the position shown in Fig. 12 to that shown in Fig. 30 14, the panel stop is eased down under the control of the counterweight 453 into its panel stopping position. Also rigidly secured to the shaft (Fig. 8) as by a pin is an arm 458, which is pivoted by means of a pin 459 to a connecting rod 35 460 (Figs. 5, 8 and 12). The lower end of the connecting rod 460 is pivotally secured, by means of a pin as shown at 461, to a lever 462. The lever 462 is curved, as shown, and has its opposite end pivoted at 463 to the side stand. Intermediate the ends of the lever is secured a stub shaft 464 which carries a roller 465.

Carried by a bracket 466 secured to the main frame of the machine (Figs. 12, 14 and 16) is a short shaft 467, the other end of which is journaled in the main frame and projects therethrough, as shown at 468. The outer end of the shaft 467 has rigidly secured thereto a cam disc 469 (Figs. 5, 16, 21, 22 and 23). The cam disc 469 has a relatively wide face which is provided with a plurality of crosswise slots 470. In this case four slots are shown, although more or less slots may be provided depending upon the number of cleats to be nailed with the panel stop up. Mounted on the periphery of the cam disc 50 55 469 are a plurality of cams 476. The cams are mounted on the face of the disc by an adjustable connection comprising studs 477 secured, as by threading, to the under surface of the cams. Since each of the cams and their mountings are 60 the same, a description of one will suffice.

The stud extends through the slot 470, and on its lower end is provided with a spring 478. One end of the spring 478 seats against a washer 479, held in position by a pin, and the other end bears 65 against the inner periphery of the cam disc 469. Thus the cam 476 is releasedly held against the face of the cam disc. Secured to the under surface of each of the cams 476 are a pair of pins 480. The pins 480 are adapted to register with 70 apertures 481 formed in the face of the cam disc. As shown in Fig. 22, two pairs of apertures are provided for each cam. By lifting upward on the cam the spring 478 may be compressed sufficiently to release the pins 480 from their apertures. The 75

cam may then be moved along the slot 470 to a position such that the pins 480 register with the other pair of apertures 481. In this manner the cams may be moved to and from the active position shown in the upper part of Fig. 22. In the active position of the cams, they lie in the path of the roller 465, so that as the cam disc 469 rotates, the cams engage the roller 465, thereby depressing the lever 462 and the connecting rod 460, and thereby raising the panel stop 441 from the position shown in Fig. 14 to that shown in Fig. 12.

In the drawings we have shown four cams 476. If a panel such as that shown in Fig. 4 is to be constructed, in which only a central cleat B is to be nailed in position, only a single cam 476 need be in its effective position. That is, when five cleats are to be nailed to the plyboard, as shown in Fig. 4, the panel stop 441 need only be in the raised position, shown in Fig. 12, during the operation of sliding the ply-board A into the position shown in Fig. 12, the nailing operation and the operation of moving the panel from the position shown in Fig. 12 to that shown in Fig. 14.

In nailing five cleats to the panel the treadle 51 is depressed five times, so that the cross-head is brought down five times to complete what may be termed a cycle of operation. Since the panel stop 441 need be in the up position only during one of these cleat nailing operations, only a single cam 476 need be in the effective position. As will be later described, the shaft 467 is rotated one fifth of a revolution, in making a five-cleat panel, for each rotation of the main shaft 92.

The cam 476 need not occupy one fifth of the circumference of the cam disc 469, partly because the shaft 467 is stationary, during the first half of the rotation of the main shaft as will presently be described. It is merely necessary that the cam be in effective position in engagement with the roller 465 prior to the start of the operation nailing the cleat B in position and at the termination thereof, so that the panel stop will be in the up position prior to the start of this portion of the cycle and for a sufficient length of time after this portion of the cycle to enable removal of the ply-board from the position shown in Fig. 12. When the roller drops off the cam the panel stop does not drop immediately to its lower position. Instead it gradually descends under the influence of the counterweight 453. When six cleats are to be nailed to a sheet of ply-board, two cams 476 are placed in effective position, and when a seven cleat panel such as that shown in Fig. 46 is to be made, three cams are placed in effective position. When an eight-cleat panel is to be made, four cams are used.

The shaft 467 is driven from the main shaft 92. On the main shaft 92 is rigidly mounted by means of a key 486, an eccentric disc 487 (Figs. 1 and 16). Surrounding the eccentric disc 487 is an eccentric strap 488, which has a rearwardly extending arm 489 formed integral therewith. The end of the arm 489 is bifurcated, as shown at 490 (Fig. 16), and the bifurcated ends are provided with apertures for the reception of a pin 491. Rigidly secured to the pin 491 is a member 492 which extends, as shown in Fig. 20, through a slot 493 formed in an arm 494, rigidly clamped to the shaft 467. The member 492 is releasably clamped to the arm 494, as shown at 495. The arm 494 is provided with notches 496, indicated by the numerals 5, 6, 7 and 8, representing numbers of cleats. When a five-cleat panel is to be made, the member 492 is clamped

to the arm in the position indicated by the numeral 5. When a six-cleat panel is to be made, the member 492 is clamped to the arm in registry with the numeral six on the arm 494. If seven or eight-cleat panels are to be made, the member 492 is clamped in position to the arm in registry with the numerals 7 or 8.

Extending rearwardly from the hub of the arm 494 is a bracket 501. The bracket at its outer end carries a cross-member 502, which has a longitudinal bore 503, for the reception of a pin 504. On the ends of the pin are loosely mounted pawls 505 and 506. The ends of the pawls have angularly shaped portions 507 against which springs 508 are adapted to press. The springs 508 are carried by the bracket 501, as shown at 509. The springs 508 will releasably retain the pawls in either of two positions: either in engagement respectively with a pair of ratchet wheels 510 and 511; or out of engagement therewith. The ratchet wheels 510 and 511 are rigidly fixed to the shaft 467 (Fig. 20), by means of set screws 512. The ratchet wheel 510 is provided with forty teeth, while the ratchet wheel 511 is provided with forty-two teeth.

As shown in Fig. 18, when the main shaft 92 is rotated, during the latter half of its rotation with the member 492 set along the arm 494 so as to register with the numeral 5, the ratchet, through the engagement of the pawl 505 therewith, will rotate through one fifth of a revolution, or 72°. During the first half of the rotation of the main shaft 92, the pawl ratchets over the wheel, back to the position shown in Fig. 18. Thus with each complete rotation of the main shaft, the shaft 467 rotates through one fifth of a revolution, so that during a complete cycle of operation, in which five cleats are nailed to a sheet of ply-board as shown in Fig. 4, the shaft 467 will have made a complete rotation. Rotation of the shaft 467 rotates the cam disc 469 (Fig. 21), and during one fifth of a cycle, the roller 465 is in engagement with a cam 476, so as to retain the panel stop 441 in the uppermost position. The shaft 467 is only rotated during the last half of the rotation of the main shaft 92, and due to the provision of the counterweight 453, the panel stop 441 moves downward slowly.

In making a five-cleat panel, at the start of a cycle, the roller 465 is in engagement with the cam 476, so that the panel stop is in the raised position shown in Fig. 12. Upon depressing the treadle, the cross-head is moved downward during the first half rotation of the main shaft 92 to nail the central cleat B to the ply-board A with the ply-board in the position shown in Fig. 12. During the last half of the rotation of the shaft 92, the cross-head is moving upward and the shaft 467 is being rotated to rotate the cam disc 469 and move the cam 476 out of engagement with the roller 465. After the roller drops off the cam, the panel stop slowly drops to the position shown in Fig. 14 under the retarding influence of the counterweight 453. After the parts are in the position shown in Fig. 14, end 65 cleats C and D and the two side cleats E are nailed in position. Since the shaft 467 rotates one-fifth of a revolution during the nailing of each cleat, during the last half of the stroke of the cross-head in nailing the last of the five 70 cleats, the cam disc 469 is rotated so that the cam 476 is again in engagement with the roller 465. The panel stop is then in the up position so that the machine is in condition to start a new cycle of operation.

When eight cleats are to be nailed to a sheet of ply-board, the member 492 is shifted so that the member 492 is in registry with the numeral 8 on the arm 494. The throw of the arm 494 is 5 then decreased so that the shaft at each complete rotation of the main shaft 92 is rotated only one-eighth of a revolution, or 45°. The ratchet 510, as mentioned above, has forty teeth so that it is suitable for use to include the nailing 10 of either five or eight cleats, since forty is evenly divisible by five or eight.

However, when six or seven cleats are to be nailed to a sheet of ply-board, the pawl 505 is shifted out of engagement with the ratchet wheel 15 510 and into the position shown in Fig. 19. The pawl 506 is moved into engagement with the ratchet wheel 511 and operation of the shaft 487 is controlled by the pawl 506 and the ratchet wheel 511. The ratchet wheel 511 has forty-two 20 teeth and when the member 492 is properly set with respect to the arm 494, the shaft 487 will be rotated one-sixth or one-seventh of a rotation for each complete rotation of the main shaft 92, depending upon the position of the member 492 25 with respect to the arm 494. The ratchet 511 is thus used in making a six-cleat panel, or a seven-cleat panel as shown in Fig. 46.

As previously mentioned, when a six, seven or eight cleat panel is to be made, additional cams 30 476 are moved into the active position in which they will engage the roller 465 as the cam disc 469 rotates. Thus if three cams are in position, the panel stop 441 is retained, in the position shown in Fig. 12, during three complete rotations of the main shaft 92 to enable the nailing 35 in position of the central cleat B and the two intermediate cleats F. After these cleats have been nailed in position, the roller 465 drops off the cams 476 and the panel stop drops to the 40 position shown in Fig. 14, in which position the top and bottom cleats C and D, and the two side cleats E, may be nailed in position.

For the purpose of guiding the panel, a panel 45 guide, generally indicated by the numeral 521, is provided at the lefthand side of the machine (Fig. 7). The panel guide 521 is provided with a slot 522 and is slidable as a whole on guides 523 provided on the top of the table. On the panel guide 521 is a stop 524 against which the side 50 edge of the ply-board is butted prior to and during the nailing of the central cleat B, the intermediate cleats F, and the end cleats C and D. By means of studs and nuts 525, the panel guide may be adjusted along the guides 523, and the 55 stop 524 secured in the position desired. Mounted on the panel guide 521 is a member 526 adjustable by means of slot and bolt connections 527. The adjustable member 526 has an abutment 528 which provides a second stop against 60 which the edge of the panel is butted, as shown in dotted lines in Fig. 7, prior to and during the nailing operations. The cleats are positioned with their end edges in engagement with the side edge of the panel guide 521 as shown in Fig. 65 7. If the side cleats E of Fig. 4 are an inch and a half wide, the stop 524 and the abutment 528 are adjusted so that they are to the left, as viewed in Fig. 7, an inch and a half from the edge of the panel guide 521. This properly 70 spaces the ends of the cleats B, C and D so that the side cleats may be laid along the side of the ply-board, butting the ends of the cleats B, C and D and flush with the edge of the ply-board.

On the angle bars 68 (Fig. 7) supporting the 75 plate 71 is adjustably mounted a pair of brackets

533, which carry an angle bar 534. The angle bar 534 limits the most rearward position of the end of the ply-board when the central cleat is to be nailed in position. The angle bar 534, by loosening the brackets 533 is adjustable along 5 the angle bars 68, so as to position the angle bar 534 in proper relationship with the cleat stop and so as to enable the accommodation of different lengths of ply-board. The angles 68 may be graduated to enable proper positioning of the 10 stops.

Also mounted on the lefthand angle bar 68, as shown in Figs. 42-45, inclusive, is an intermediate panel stop generally indicated by the numeral 538. The stop 538 comprises a U- 15 shaped brack 539 adjustably held in position on the angle bar 68 by means of a set screw 540. A pin 541 pivotally carries a stop element 542. As shown at 543 the stop element 542 is beveled so that it may be raised by sliding a 20 sheet of ply-board sidewardly into engagement with the stop element. The front face 544 of the stop element serves as an abutment for the end of the ply-board when, for example, the intermediate cleats F of a seven-cleat panel are to 25 be made. However, when the central cleat of a five or seven-cleat panel is to be nailed on the 30 ply-board, the ply-board may be placed on the table and slid rearwardly and sidewardly so that the ply-board cams the stop element 542 upward, so that the edge of the ply-board may engage the stop 524 (Fig. 7), and the end of the 35 ply-board may engage the angle bar 534. The manner in which the ply-board is slid past and beneath the stop element 542 is shown in Fig. 42. In nailing an intermediate cleat for example the cleats F of a seven-cleat panel shown in Fig. 46, the ply-board is pushed straight rearwardly so that the end of the ply-board A engages the 40 face 544 of the stop element 542 so that the 45 ply-board is in the proper position for the reception of one of the intermediate cleats F. By adjusting the intermediate panel stop 538 along the angle bar 68, the intermediate cleats may be 50 properly spaced with respect to the central cleat B. Additional stop elements, similar to the stop element 542 may be used to further increase the flexibility of the machine to the nailing of any number of cleats in any desired position.

As previously mentioned, the machine is arranged so that twelve nails are simultaneously driven when short cleats are to be nailed in position and thirty nails are simultaneously driven when long cleats are to be nailed in position. As diagrammatically shown in Fig. 27, the two 55 lefthand nail feed discs 232 are provided with five nail slots 233 so that these nail discs feed a nail to their respective nail chucks at each operation of the main shaft 92. This is true of the twelve nail feed discs at the extreme left of 60 the machine. The remainder of the nail feed discs are provided with only two nail slots 233 as shown by the two righthand nail feed discs 232 of Fig. 27. These nail feed discs feed only two nails to their respective nail chucks during 65 a complete cycle of operation. The feeding of nails to the nail chucks occurs in proper timed relation with the sequence of operations of the machine, so that the nails are in position for driving in the nail chucks at the proper time in 70 the cycle of operation. In the case of the eighteen nail feed discs at the righthand side of the machine, the discs are timed so that they feed nails to their nail chucks only just prior to the 75 nailing of long cleats. Of course the number of

nails driven into the short cleats may be increased or decreased, as desired, by increasing the number of nail feed discs 232 which have five nail slots. This would be desirable if longer short cleats than those shown in Figs. 4 and 46 were to be nailed to a sheet of ply-board. Moreover, if the long cleats are shorter than those shown in Figs. 4 and 46, one or more nail feed discs 232 at the righthand side of the machine 5 may be blanks or the nail slots leading to these discs may be shut off. That is, the nail slots 233 in these discs may be omitted so that they will not feed any nails to their nail chucks.

In Fig. 28 two nail discs 232 have been shown 15 at the left of this figure provided with seven nail slots 233. These nail discs are representative of the twelve nail feed discs at the left of the machine. The remainder of the nail feed discs are provided with two nail slots. This 20 setting of the machine is for the purpose of making a seven-cleat panel such as that shown in Fig. 46, wherein five short cleats and two long cleats are nailed to the ply-board. A nail is fed to each of the twelve nail chucks at the left 25 of the machine during seven successive operations of the main shaft, constituting the cycle of operation of the machine in making a seven-cleat panel. During the last two operations of the main shaft the eighteen nail discs at the 30 right of the machine come into operation and feed nails to their respective nail chucks. When six or eight-cleat panels are to be made the nail discs shown in Figs. 27 and 28 must be changed accordingly as will be obvious. In the case of a 35 six-cleat panel, the twelve nail discs at the left of the machine will be provided with six nail slots, and in the case of an eight-cleat panel the twelve nail feed discs at the left of the machine will be provided with eight nail slots.

40 As previously mentioned, when the machine is to be changed from a setting for a five-cleat panel to a setting for a six, seven or eight-cleat panel, the gear 186 (Fig. 25) is removed and replaced. The substituted gear is of such size 45 as to drive the nail feed discs at the proper speed for rotating the discs once during a cycle of operation of the machine, the cycle of operation being six, seven, or eight (or more if desired) rotations of the main shaft depending upon the 50 number of cleats to be nailed. That is, for example, in the case of a six-cleat panel the gear 186 should be of such a size that it will drive the nail feed discs one sixth of a revolution for each rotation of the main shaft 92, while if a 55 seven-cleat panel is to be made, the gear 186 must be changed so that the substituted gear will rotate the nail feed discs one seventh of a revolution for each complete rotation of the main shaft 92. In addition, as previously mentioned, 60 when changing the machine for making a six, seven or eight-cleat panel the setting of the member 492 with respect to the arm 494 must be changed and the proper ratchet wheel 510 or 511 must be used.

65 While the operation of the machine has been described during the description of the parts of the machine, a short summary of the operation may be helpful to an understanding of the machine. The machine is preferably controlled by 70 two operators, one of which handles the cleats and the other the ply-board. In making a five-cleat panel, the central cleat B (Fig. 4) is placed in position with its end against the side edge of the panel guide 521 (Fig. 7) and its side edge 75 against the cleat stop 346. The panel is then

pushed rearwardly on the table and slightly side-wardly to raise the stop element 542 of the stop 538 and permit the panel to be slid to the position shown in Fig. 42. (If desired, the stop 538 may be removed during the making of five-cleat panels as it is not used in these operations.) When the ply-board is in engagement with the angle bar 534 the treadle 51 is actuated which engages the clutch 159 with the drive gearing and causes the cross-head 52 to move downward. 10 The cross-head in moving downward first causes engagement of the ends of the nail chucks with the top surface of the ply-board. Simultaneously or preferably just prior thereto, the cleat fingers 347 and 347' are brought into operative engagement, as shown in Fig. 12, with the cleat for holding the cleat rigidly in position. The continued rotation of the main shaft 92 brings the cross-head down and drives the nails, by means of the drivers 298, through the ply-board and the 20 cleat. In connection with the table there is provided a nail clincher for bending the lower ends of the nails so that they lie flush with the bottom surface of the cleat (see Figs. 38 and 39). The nail clincher constitutes no part of the present 25 invention, and since nail clinchers of a suitable type are well known in the art to which this invention applies, need not be particularly described. The nail clincher may be similar to that shown in United States Letters Patent No. 30 1,842,796, issued January 26, 1932, to Henry W. Morgan. The continued rotation of the main shaft, after the nailing operation has been completed, restores the cross-head to its up or normal position. The panel is pulled outward from 35 the position shown in Fig. 42 after which the panel stop 441 drops from the position shown in Fig. 12 to the position shown in Fig. 14.

A cleat C is then placed in position against the abutment 528 and the cleat stop 346. The 40 ply-board is then moved into engagement with the panel stop 441 and flush with the edge of the cleat. The foot treadle is then again operated to perform a second nailing operation. The panel is then turned around and the short wide 45 cleat slid into nailing position. If it is desired to stagger the nails, as previously described, the hand lever 409 is pulled forwardly, thereby moving the nail chuck bar 281 with respect to the nail chuck bar 280, so that the nail chucks will be 50 in staggered relation and the nails driven into the wide cleat in the staggered relation shown on the cleat D in Fig. 46. After the wide cleat has been nailed in position one of the side cleats E is placed in nailing position. When the side 55 cleats E are to be nailed the panel is not brought over to the position shown in Fig. 7, but instead, is positioned so that the outer side edge of the cleat C is in alignment with the side edge of the panel guide 521 so that the ends of the side cleat E will lie flush with the ends of the ply-board. During the nailing of the side cleats E, the eighteen nail feed discs at the right of the machine are in operation feeding nails to their respective nail chucks so that thirty nails are 60 simultaneously driven into the ply-board and cleat. After both side cleats have been nailed into position during the last portion of the cycle, that is, during the raising of the cross-head after the nailing of the last cleat, the cam disc 469 65 (Fig. 21) rotates so that the roller 465 is in engagement with a cam 476 and the panel stop 441 is moved to the raised position shown in Fig. 12, ready for the start of another cycle. As previously mentioned, prior to the nailing of each of the 70 75

side cleats E, one of the operators must actuate the push rod 333 so as to set the machine for nailing long cleats, as shown in Figs. 37 and 38.

In making a seven-cleat panel the operations 5 are the same, except that after nailing the central cleat B, the two intermediate cleats F are nailed before the end cleats C and D. The panel is properly positioned for nailing the intermediate cleats F by the stop 538 shown in Figs. 42-45, inclusive. It will be appreciated that with the exception of the hoppers, which are driven continuously, all of the other parts are driven from the main shaft 92. The number of intermittent rotations of the main shaft required for completing a panel or a cycle of operation is dependent upon the number of cleats to be used in forming the panel. The panel stop 441, the cleat fingers 347, the nail feed discs 232, and the cross-head are driven in timed relation from the main shaft 92, so that the parts are actuated at the proper time during the cycle of operation.

It will be appreciated that the machine of this invention is extremely flexible in that it is adapted to the making of panels having any desired number of cleats of any length, width or thickness, within the capabilities of the machine, in accordance with the requirements of the particular packing case or container to be built. Moreover, the machine may be used to nail sections of boards together rather than for nailing cleats. In addition, several of the improvements disclosed herein are useful on other types of nailing machines. It will further be appreciated that while a specific embodiment of the invention has been described, various changes and modifications may be made, particularly in the form and relation of parts, without departing from the spirit of this invention as set forth in the appended claims.

40 We claim:

1. In a machine for nailing cleats on a sheet of board material, in combination, a surface having a nailing position, means including a stop for locating a cleat in said nailing position, means 45 including a movable stop for locating a board with its edge in the same vertical plane as the edge of the cleat, means for moving said stop so as to enable the nailing of a cleat on a line remote from the edges of the board, and means for nailing the cleat and the board to each other.

2. In a machine for nailing cleats on a sheet of board material, in combination, a surface having a nailing position, means including a cleat stop for locating a cleat in said nailing position, 55 a remote stop for locating a board in proper position for nailing a substantially central cleat to the board, an intermediate stop for locating the board for nailing an intermediate cleat to the board, a movable stop for positioning the board 60 for nailing an edge cleat to the board, means for moving said movable stop to enable the board to be moved past said movable stop to enable the nailing of said central and intermediate cleats, and means for nailing the cleats and the board 65 to each other.

3. In a machine for nailing cleats on a sheet of board material, in combination, a surface having a nailing position, means including a stop for locating the board in proper position for nailing a substantially central cleat to the board, means 70 including a movable stop for locating the board in proper position to nail an edge cleat to the board, means for raising said last-mentioned stop for enabling the positioning of said board in engagement with said first-mentioned stop, and

means for nailing the cleats and the board to each other.

4. In a machine for nailing cleats on a sheet of board material, in combination, a surface having a nailing position, means including a cleat stop for locating a cleat in said nailing position, 5 a board stop having a face lying normally in the same plane as said cleat stop, means for raising said board stop so that the board may be pushed on said surface beyond said cleat stop for enabling the nailing of a cleat spaced from the edges of the board, means for lowering said board stop so that the board stop and the cleat stop are in alignment to enable the positioning of the edge of the board flush with an edge cleat to enable 10 the nailing of an edge cleat to the board, and means for nailing said cleats and the board to each other.

5. In a nailing machine, in combination, a surface upon which the parts to be nailed are placed 20 and having a nailing position, a stop, means for nailing the parts together, comprising a shaft, and means driven from said shaft for raising and lowering said stop, comprising a second shaft 25 driven from said first shaft, and ratchet and pawl mechanism mounted on said second shaft for operating said stop.

6. In a nailing machine, in combination, a board stop, and means for raising and lowering 30 said board stop, comprising a shaft, a pair of ratchets mounted on said shaft, said ratchets having a different number of teeth, a pair of pawls each cooperable with one of said ratchets and selectively movable into engagement therewith.

7. In a nailing machine, in combination, a shaft, nailing means driven from said shaft, a surface having a nailing position, a guide for locating a board to be nailed, and means for moving 40 said guide into and out of operative position in timed relation to rotation of said shaft, said means including a second shaft driven from said first shaft, said second shaft having a cam mounted thereon.

8. In a nailing machine, in combination, a 45 surface upon which the parts to be nailed are placed and having nailing position, a stop, means for nailing the parts to each other, comprising a shaft, and means driven from said shaft for raising and lowering said stop, said means comprising a cam disc having a plurality of cams mounted thereon, said cams being selectively movable into and out of operative position.

9. In a machine for nailing cleats on a sheet of board material, in combination, a shaft, nailing 55 means driven from said shaft, a surface having a nailing position, a guide for locating the board to which a cleat is to be nailed, and means for moving said guide into and out of operative position in timed relation to the rotation of said shaft, comprising a second shaft driven from said first shaft, a pawl and ratchet on said second shaft for driving said second shaft through a partial rotation during the rotation of said first shaft, a cam mounted on said second shaft, and 60 means driven by said cam for raising and lowering said guide.

10. In a nailing machine of the class described, a finger, means for moving said finger into and out of engagement with a part to be nailed, comprising 70 a shaft, a cam on said shaft, a connecting rod driven by said cam, an arm connected to said connecting rod and connected to said finger, a spring on said rod through which the force of said cam is transmitted to said arm, and means 75

in connection with said arm for enabling said arm to yield when the resistance offered by the part is greater than desired.

11. In a machine of the class described, a surface having a nailing position, means for supporting a cleat in said nailing position, cleat engaging means movable to and from a position engaging said cleat for holding the cleat while being nailed, means including resilient connections for moving said cleat engaging means into engagement with the cleat, said resilient connections being adapted to exert a predetermined normal pressure on a relatively narrow cleat, and means in said connections effective only when a relatively wide cleat is supported in said nailing position for preventing successive pressure on said wide cleat.

12. In a machine of the class described, a surface having a nailing position, means including a fixed stop for supporting a part to be nailed in said nailing position, a plurality of fingers movable to and from a position engaging said part for holding the part while being nailed, means for moving said fingers into engagement with the part, said means comprising a cam, a plurality of arms and a resilient connection between said cam and arms, certain of said arms being in two sections, and spring means between said sections effective when a relatively wide part is placed in said nailing position for preventing excessive pressure on said wide part.

13. In a nailing machine, a surface having a nailing position, means for supporting the parts to be nailed in said nailing position, means including a plurality of nail chucks for nailing the parts together, means for maintaining said nail chucks in a straight line so that the nails are driven in a straight line, and means for staggering said nail chucks so as to drive the nails in staggered relation, if desired, said means being operable to stagger said nail chucks without interrupting the normal operation of the machine.

14. In a machine for nailing cleats to a sheet of board material, a surface having a nailing position, means for supporting a cleat and the board to which the cleat is to be nailed in said nailing position, means including a plurality of nail chucks for nailing the cleat to the board, means for maintaining said nail chucks in a straight line so that the nails are driven in a straight line, means for staggering said nail chucks so as to drive the nails in staggered relation if desired, said means including a plurality of nail chuck bars upon which the nail chucks are mounted, and means for moving said nail chuck bars relative to each other to stagger the nails in the same cycle of operation, said means including guide means in which at least one of said chuck bars is slideable and a hand operated member for shifting said chuck bar in said guide means.

15. In a machine for nailing cleats to a sheet of board material, in combination, a surface having a nailing position, a stop for the board and the cleats to be nailed to the board, said stop being in two parts, and means for moving one of said parts with respect to the other to enable the board to be pushed between and beyond said stops to enable the nailing of a cleat to the board in a position spaced from the edges of the board.

16. In a machine for nailing cleats to a sheet of board material, in combination, an intermittently operated main shaft, means for nailing cleats to the board driven from said shaft, said shaft being operated a number of times to com-

plete a cycle of operation defined by the nailing of a full complement of cleats to the board, a stop for positioning the board and the cleats with respect to the board when an edge cleat is to be nailed in position, said stop being in two parts, and means driven from said main shaft for automatically moving one of said parts with respect to the other during said cycle of operation to enable the board to be pushed between and beyond said stop to enable the nailing of a cleat to the board in a position spaced from the edges of the board.

17. In a machine for nailing cleats to a sheet of board material, in combination, an intermittently operated main shaft, means for nailing cleats to the board driven from said shaft, said shaft being operated a number of times to complete a cycle of operation defined by the nailing of a full complement of cleats to the board, a stop for positioning the board and the cleats with respect to the board when an end cleat is to be nailed in position, said stop being in two parts, means driven from said main shaft for automatically moving one of said parts with respect to the other during said cycle of operation to enable the board to be pushed between and beyond said stop to enable the nailing of a cleat to the board in a position spaced from the ends of the board, and means driven from said shaft movable into and out of engagement with the cleats each time the shaft is operated for holding the cleats against said stop during the nailing operation.

18. In a machine for nailing a variable number of cleats to a sheet of board material, in combination, a plurality of nail chucks, a hopper for containing the nails, means including a plurality of nail feed elements for feeding the nails from said hopper to said nail chucks, means for driving the nails from said nail chucks into a board and the cleat to be nailed to the board, and means whereby the speed of operation of said nail feed elements may be varied in accordance with the number of cleats to be secured to the board.

19. In a machine for nailing a variable number of parts together, in combination, a plurality of nail chucks, a hopper for containing nails to be fed to the nail chucks, means including a plurality of nail feed elements for feeding the nails from said hopper to said nail chucks, means for continuously oscillating said hopper to feed the nails from said hopper to said nail feed elements, means including an intermittently operated shaft for driving the nails from said nail chucks into the parts to be nailed, said nail feed elements being driven from said shaft, and means whereby the speed for operation of said nail feed elements may be varied in accordance with the number of parts to be nailed without varying the speed of operation of said shaft.

20. In a nailing machine, in combination, means including an intermittently operable main shaft for driving nails, continuously rotating driving means for said main shaft, a hopper for containing the nails, means for driving said hopper from said continuously rotating driving means for continuously operating said hopper when said shaft is operating or stationary, and latch means for said hopper for discontinuing the operation of said hopper, when desired.

21. In a nailing machine for nailing cleats to a sheet of board material, in combination, a hopper for containing nails, continuously operating means for operating said hopper to feed the nails to the machine, and means for disconnecting said hopper from said continuously operating

means when desired, said means comprising a latch element carried by the machine and a latch element movable with said hopper.

22. In a nailing machine, in combination, 5 means for securing the parts to be nailed together, comprising a plurality of nail drivers and a driving head for said nail drivers, and means for compensating for the difference in resistance to the driving action of said head when less than 10 a full complement of nails are being driven so that the nails are driven with their heads flush with the board surface both when a full complement of nails are being driven and when a lesser number are being driven.
- 15 23. In a nailing machine, in combination, means for securing the parts to be nailed to the board comprising a plurality of nail drivers and a driving head having a nail driver engaging surface, and means for compensating for the 20 difference in resistance to the driving action of said head when less than a full complement of nails are being driven so that the nails are driven with their heads flush with the board surface both when a full complement of nails are 25 being driven and when a lesser number are being driven, said means comprising means for raising and lowering the nail driver engaging surface of the head.
- 30 24. In a nailing machine, nail feed mechanism 30 for feeding the nails to be driven, said nail feeding mechanism comprising a plurality of nail feeding members, and a plurality of worms, each adapted to drive a plurality of said nail feeding members, a coupling between said worms for 35 enabling the worms to be driven from a single source of power, and means in connection with said coupling whereby one worm may be advanced with respect to the other to enable synchronization of the nail feeding members driven by two adjacent worms.
- 40 25. In a nailing machine, nail feeding mechanism for feeding the nails to be driven, said nail feed mechanism comprising a plurality of nail feed members, a shaft for driving said nail feed members, a gear train for driving said shaft, a bracket for carrying certain of the gears of said gear train, said bracket being pivoted to enable movement of said gears out of engagement with a gear of the train to enable convenient removal of a gear and the substitution of another gear adapted to drive said nail feed members at a 45 higher or lower speed.
- 50 26. In a machine for nailing a plurality of cleats to a sheet of board material to form a panel of rectangular shape, in combination, a main shaft, a table having a nailing position, a cleat stop mounted on said table for receiving the side edge of a cleat, cleat engaging means driven by said shaft and movable into and out of engagement with the cleat, said cleat stop and cleat engaging means cooperating to hold the cleat rigidly in said nailing position during the nailing operation, a board stop having a surface in vertical alignment with said cleat stop, means driven from said shaft for raising the board stop to enable a board to be slid over said table surface beyond the cleat stop to enable the nailing of a cleat spaced from the ends of the board, nailing means including a plurality of nail chucks, means driven from said shaft for operating the nailing means to secure said cleat to the board, means for lowering said board stop after the board has been moved from its position beyond the cleat stop so that said cleat stop and said surface of the board stop are in vertical alignment, means 55
- 60
- 65
- 70
- 75

for nailing a pair of end cleats to opposite ends of the board with the side edges of the cleats in alignment with the ends of the board, means for nailing a pair of side cleats to the board with the side edges thereof flush with the side edges 5 of the board, the nailing of said cleats to complete the panel constituting a cycle of operation, and means driven from said shaft for varying automatically the number of chucks supplied with nails at different portions of the cycle, to 10 thereby enable the driving of a greater number of nails in the cleats of greater length.

27. In a machine for nailing a plurality of cleats to a sheet of board material to form a panel of rectangular shape, in combination, a main shaft, a table having a nailing position, a cleat stop mounted on said table for receiving the side edge of a cleat, cleat engaging means driven by said shaft and movable into and out of engagement with the cleat, said cleat stop 20 and cleat engaging means cooperating to hold the cleat rigidly in said nailing position during the nailing operation, a board stop having a surface in vertical alignment with said cleat stop, means driven from said shaft for raising the 25 board stop to enable a board to be slid over said table surface beyond the cleat stop to enable the nailing of a cleat spaced from the ends of the board, nailing means including a plurality of nail chucks, means driven from said shaft for 30 operating the nailing means to secure said cleat to the board, means for lowering said board stop after the board has been moved from its position beyond the cleat stop so that said cleat stop and the surface of the board stop are in vertical 35 alignment, means for nailing a pair of end cleats to opposite ends of the board with the side edges of the cleats in alignment with the ends of the board, means for nailing a pair of side cleats to the board with the side edges thereof flush with the side edges of the board, the nailing of said 40 cleats to complete the panel constituting a cycle of operation, means driven from said shaft for varying automatically the number of chucks supplied with nails at different portions of the 45 cycle, to thereby enable the driving of a greater number of nails in the cleats of greater length, and means for staggering the chucks to enable the staggering of the nails at any part of said cycle of operation.

28. In a machine for nailing cleats on a sheet of board material, in combination, a surface having a nailing position, means including a stop for locating a cleat in said nailing position, means including a movable stop for locating a board above the cleat with its edge in the same vertical plane as the edge of the cleat, said movable stop when moved enabling the board to be moved beyond said movable stop to enable the nailing of a cleat to the lower side of the board on a line 60 remote from the edges of the board, and means for nailing the cleats and the board to each other.

29. In a machine for nailing cleats on a sheet of board material, in combination, a surface having a nailing position, means including a stop for locating a cleat in said nailing position, means including a movable stop for locating a board above the cleat, said two stops having the portions thereof which engage the work lying in the 65 same plane, said movable stop when moved enabling the board to be moved beyond said movable stop over the first-mentioned stop to enable the nailing of the cleat to the under side of said board on a line remote from the edges of the 70

50

55

60

65

70

75

board, and means for nailing the cleats and the board to each other.

30. In a machine for nailing cleats on a sheet of board material, in combination, a horizontally extending table surface having a nailing position, a cleat stop having a cleat engaging face extending above the level of said table surface and at least partly defining said nailing position, a movable board stop superimposed upon said cleat stop for locating a board above the cleat with its edge in the same vertical plane as the edge of the cleat, said movable stop when moved enabling the board to be moved over the cleat stop and table beyond said cleat stop to enable the nailing of a cleat to the board on a line remote from the edges of the board, and means for nailing the cleats and the board to each other.

31. In a machine for nailing cleats on a sheet of board material, in combination, a surface having a nailing position, means including a cleat stop for locating a cleat in said nailing position, a remote stop for locating a board in proper position for nailing a substantially central cleat to the board, an intermediate stop for positioning the board for nailing an intermediate cleat to the board, a movable stop for positioning the board for nailing an edge cleat to the board, the work engaging parts of said cleat stop and said movable stop lying in the same plane, said movable stop when moved enabling the board to be moved over said cleat stop to properly position the board in abutting relation with said remote stop and said intermediate stop to enable the nailing of said central and intermediate cleats on the under side of the board, and means for nailing the cleats and the board to each other.

32. In a machine for nailing cleats on a sheet of board material, in combination, a substantially horizontally extending table surface having a nailing position, means including a cleat stop for locating a cleat in said nailing position, a board stop superimposed upon said cleat stop and having a work engaging face lying normally in the same plane as the work engaging face of said cleat stop, said board stop being movable so as to raise said board stop so that a space exists between the board stop and the cleat stop whereby the board may be pushed on said surface over and beyond said cleat stop for enabling the nailing of a cleat spaced from the edges of the board, said board stop upon being lowered having said face substantially in vertical alignment with the face of said cleat stop to enable the positioning of the edge of the board flush with an edge cleat to enable the nailing of an edge cleat to the board, and means for nailing the cleats and the board to each other.

33. In a machine for nailing cleats on a sheet of board material, in combination, a substantially horizontally extending table surface having a nailing position, means including a cleat stop for locating a cleat in said nailing position, a board stop superimposed upon said cleat stop, and having a work engaging face lying normally in the same plane as the work engaging face of said cleat stop, said board stop being movable so as to raise said board stop so that a space exists between the board stop and the cleat stop whereby the board may be pushed on said surface over and beyond said cleat stop for enabling the nailing of a cleat spaced from the edges of the board, said board stop upon being lowered having said face substantially in vertical alignment with the face of the cleat stop to enable the positioning of the edge of the board flush

with an edge cleat to enable the nailing of an edge cleat to the board, and means for nailing the cleats and the board to each other with the cleats on the underside of the board.

34. In a nailing machine, in combination, a shaft, nailing means driven from said shaft, a surface having a nailing position, a stop at least partly defining said nailing position, said stop being in two parts, the work engaging faces of said parts normally lying in the same plane and said parts being superimposed with respect to each other, and means for moving one of said parts into and out of said superimposed operative position in timed relation to the rotation of said shaft.

35. In a nailing machine of the class described, a surface having a nailing position, means including a fixed stop for supporting a part to be nailed in said nailing position, a finger movable to and from a position engaging said part for holding the part while being nailed, means for moving said finger into engagement with the part, said means comprising a power driven element, an arm and a compression spring through which the force of said power driven element is transmitted to said arm, and means in connection with said arm for enabling said arm to yield independently of said compression spring when the resistance offered by the part is greater than desired.

36. In a machine of the class described, a surface having a nailing position, means including a fixed stop for supporting a part to be nailed in said nailing position, a plurality of fingers movable to and from a position engaging said part for holding the part while being nailed, means for moving said fingers into engagement with the part, said means comprising a power driven element, a plurality of arms and a resilient connection between said power driven element and said arms at least some of said arms being in two sections, and spring means between said sections effective when a relatively wide part is placed in position to prevent the pressure on said part from being excessive.

37. In a nailing machine, a surface having a nailing position, means for supporting a part and a board to which the part is to be nailed in said nailing position, a shaft, a plurality of nail chucks, nail driving means driven from said shaft for driving the nails, means for feeding nails to each of said nail chucks when a long part is to be nailed to the board, means for feeding nails only to certain of said chucks when a shorter part is to be nailed to the board, and means whereby the speed of operation of said nail feeding means may be varied without varying the speed of rotation of said shaft.

38. In a machine for nailing a variable number of cleats of variable length to a board, a surface having a nailing position, means for supporting a cleat and a board to which the cleat is to be nailed in said nailing position, a drive shaft, a plurality of nail chucks, nail driving means driven from said shaft for driving the nails, means for feeding nails to at least most of said nail chucks when a long cleat is to be nailed to the board, means for feeding nails to a lesser number of chucks when a shorter cleat is to be nailed to the board, and means whereby the speed of operation of said nail feeding means may be varied without varying the speed of rotation of said shaft to enable a variation in the number of cleats nailed to the board.

39. In a machine for nailing parts to a board,

a main shaft, a plurality of nail chucks, means driven from said shaft for driving the nails, said shaft rotating through one revolution each time a part is nailed to the board, means including a plurality of nail feed shafts for feeding nails to said nail chucks, said nail feed shafts being driven from said main shaft at a speed such that the nail feed shafts rotate only once during the nailing of a full complement of parts to the board, and means between the main shaft and the nail feed shafts whereby the speed of rotation of the nail feed shafts may be varied so as to rotate the nail feed shafts only through a single revolution regardless of the number of parts to be nailed to the board.

40. In a machine for nailing cleats to a sheet of board material wherein a plurality of nail chucks are provided, said nail chucks being normally approximately in alignment, means for staggering said nail chucks comprising a pair of nail chuck bars upon which the nail chucks are mounted, a rotatable member, means for connecting said rotatable member with one of said nail chuck bars, said rotatable member being manually rotatable to shift said connected chuck bar and move the nail chucks associated therewith out of alignment with the remainder of the nail chucks.

41. In a machine for nailing cleats to a sheet of board material wherein a plurality of nail chucks are provided, said nail chucks being normally approximately in alignment, means for staggering said nail chucks comprising a pair of nail chuck bars upon which the nail chucks are mounted, a rotatable member, means for connecting said rotatable member with one of said nail chuck bars, said rotatable member being manually rotatable to shift said connected chuck bar and move the nail chucks associated therewith out of alignment with the remainder of the nail chucks, and adjustable means in connection with said rotatable member for varying the amount of the staggering of the nail chucks.

42. In a machine for nailing cleats to a sheet of board material wherein a plurality of nail chucks are provided, a pair of nail chuck bars, some of said nail chucks being mounted on one of said bars and some on the other, and means for moving one of said nail chuck bars with respect to the other, said means comprising a pair of guides in which one of said bars is slidably mounted, a rotatable member, means for connecting said slidable bar with said rotatable member, adjustable stop means for determining the amount of movement of said slidable bar with respect to the other bar, and manually operable means whereby said rotatable member may be rotated to shift said slidable bar.

43. In a machine for nailing cleats to a sheet of board material wherein a plurality of nail chucks are provided, a pair of nail chuck bars, some of said nail chucks being mounted on one of said bars and some on the other, and means for moving one of said nail chuck bars with respect to the other forwardly and rearwardly of the machine, said means comprising a pair of guides in which one of said bars is slidably mounted, a rotatable member, means for connecting both ends of said slidable bar with said rotatable member, adjustable stops for determining the amount of movement of said slidable bar both forwardly and rearwardly of the machine and with respect to the other bar, and manually operable means whereby said rotatable member may be rotated to shift said slidable bar.

44. In a machine for nailing cleats to a sheet of board material, in combination, an intermittently operated main shaft, means for nailing cleats to the board driven from said shaft, said shaft being operated a number of times to complete a cycle of operation defined by the nailing of the full complement of cleats to the board, a cleat stop, a board stop, said stops normally having their working engaging faces in alignment and one of said stops being movable with respect to the other, said movable stop upon movement enabling the board to be positioned beyond said stops so as to enable the nailing of a cleat to the board in a position spaced from the edges of the board, and means driven from said shaft movable into and out of engagement with the cleats each time the shaft is operated for holding the cleats against said cleat stop during a nailing operation.

45. In a nailing machine, in combination, a plurality of nail chucks adapted to engage the work during the nailing operation, a plurality of nail drivers cooperating with said nail chucks, a driving head for said nail drivers, means for raising and lowering the head to compensate for the difference in resistance to the driving action of said head when less than a full complement of nails are being driven so that the nails are driven with their heads flush with the work surface both when a full complement of nails are being driven and when a lesser number are being driven, and means for applying a driving force to said driving head with the head in either its raised or lowered position.

46. In a nailing machine, in combination, a plurality of nail chucks adapted to engage the work during the nailing operation, a plurality of nail drivers cooperating with said nail chucks, a driving head for said nail drivers, means for raising and lowering the head to compensate for the difference in resistance to the driving action of said head when less than a full complement of nails are being driven so that the nails are driven with their heads flush with the work surface both when a full complement of nails are being driven and when a lesser number are being driven, said means including a pair of rods extending substantially across the machine and having flattened portions adapted to be moved into and out of engagement with the driving head, and means for applying a driving force to said driving head with the head in either its raised or lowered position.

47. In a nailing machine, nail feeding mechanism for feeding the nails to be driven, said nail feeding mechanism comprising a plurality of nail feeding members and a plurality of worms each adapted to drive a plurality of said nail feeding members, a coupling between said worms for enabling the worms to be driven from a single source of power, means in connection with said coupling whereby one worm may be advanced with respect to the other to enable synchronization of the nail feeding members driven by two adjacent worms, and means whereby the speed of rotation of said worms may be varied.

48. In a nailing machine, a table for the reception of the board and the parts to be nailed to the board, a guide for the board pivotally secured with respect to the table so that a portion thereof rests on the table, said guide having a beveled surface facing inward and toward the table whereby a board may be slid sidewise along the table surface to cam the guide upward about its pivot and enable the board to be slid beneath

and beyond the guide, and said guide having a forwardly facing surface acting as an abutment when the board is pushed directly against said guide.

5 49. In a machine for nailing a plurality of cleats to a sheet of board material to form a cleated panel of polygonal shape, in combination, a main shaft, a table having a nailing position, a cleat stop having a work engaging surface for 10 receiving the side edge of a cleat, means including cleat engaging elements driven by said shaft located beneath the board and movable into and out of pressure engagement with the cleat, said cleat stop and cleat engaging elements 15 engaging the cleat from opposite sides and cooperating to hold the cleat rigidly in position during the nailing operation, a movable board stop closely adjacent said cleat stop and having a work engaging surface in vertical alignment 20 with the work engaging surface of said cleat stop, said stops being arranged so that the cleat is beneath the board, said board stop upon being moved away from the cleat stop enabling a board to be slid over said table beyond the cleat stop to 25 enable the nailing of a cleat spaced from the edges of the board, nailing means including a plurality of nail chucks, and means driven from said shaft for operating the nailing means to secure said cleat to the underside of the board, 30 said board stop upon again being moved closely adjacent said cleat stop after the board has been moved from its position beyond the cleat stop enabling the nailing of end cleats to the underside of the board with the side edges of the cleats in alignment with the ends of the board and the nailing 35 of side cleats to the underside of the board with the side edges thereof flush with the side edges of the board.

50. In a machine for nailing a plurality of cleats to a sheet of board material to form a cleated panel of polygonal shape, in combination, a main shaft, a table having a nailing position, a cleat stop having a work engaging surface for receiving the side edge of a cleat, means including cleat engaging elements driven by said shaft located beneath the board and movable into and out of pressure engagement with the cleat, said cleat stop and cleat engaging elements engaging the cleat from opposite sides and cooperating to hold the cleat rigidly in position during the nailing 40 operation, a movable board stop closely adjacent said cleat stop and having a work engaging surface in vertical alignment with the work engaging surface of said cleat stop, stops being arranged so that the cleat is beneath the board, said board stop upon being moved away from the cleat stop enabling a board to be slid over said table beyond the cleat stop to enable the nailing of a cleat spaced from the edges of the board, nailing means including a plurality of nail 45 chucks, and means driven from said shaft for operating the nailing means to secure said cleat to the underside of the board, said board stop upon again being moved closely adjacent said cleat stop after the board has been moved from its position beyond the cleat stop enabling the nailing of end cleats to the underside of the board with the side edges of the cleats in alignment with the ends of the board and the nailing of side cleats to the underside of the board with the side edges thereof flush with the side edges of the board, the nailing of said cleats to complete the panel constituting a cycle of operation, and means driven from said shaft for varying automatically the number of chucks supplied with

nails at different portions of the cycle to thereby enable the driving of a greater number of nails in the cleats of greater length.

51. In a machine for nailing a plurality of cleats to a sheet of board material to form a 5 cleated panel of polygonal shape, in combination, a main shaft, a table having a nailing position, a cleat stop having a work engaging surface for receiving the side edge of a cleat, means including cleat engaging elements driven by said shaft 10 located beneath the board and movable into and out of pressure engagement with the cleat, said cleat stop and cleat engaging elements engaging the cleat from opposite sides and cooperating to hold the cleat rigidly in position during the nailing 15 operation, a movable board stop closely adjacent said cleat stop and having a work engaging surface in vertical alignment with the work engaging surface of said cleat stop, said stops being arranged so that the cleat is beneath the board, said board stop upon being moved away from the cleat stop enabling a board to be slid over said table beyond the cleat stop to enable the nailing of a cleat spaced from the edges 20 of the board, nailing means including a plurality of nail chucks, means driven from said shaft for operating the nailing means to secure said cleat to the underside of the board, said board stop upon again being moved closely adjacent said cleat stop after the board has been moved from 25 its position beyond the cleat stop enabling the nailing of end cleats to the underside of the board with the side edges of the cleats in alignment with the ends of the board and the nailing 30 of side cleats to the underside of the board with the side edges thereof flush with the side edges of the board, and means whereby the nail chucks may be staggered during the nailing of a complete set of cleats to the board without interrupting the normal operation of the machine. 35

52. In a machine for nailing a plurality of cleats to a sheet of board material to form a cleated panel of polygonal shape, in combination, a main shaft, a table having a nailing position, a cleat stop having a work engaging surface for receiving the side edge of a cleat, means including cleat engaging elements driven by said shaft located beneath the board and movable into and out of pressure engagement with the cleat, said cleat stop and cleat engaging elements 40 engaging the cleat from opposite sides and cooperating to hold the cleat rigidly in position during the nailing operation, a movable board stop closely adjacent said cleat stop and having a work engaging surface in vertical alignment 45 with the work engaging surface of said cleat stop, said stops being arranged so that the cleat is beneath the board, said board stop upon being moved away from the cleat stop enabling a board to be slid over said table beyond the cleat stop to enable 50 the nailing of a cleat spaced from the edges of the board, nailing means including a plurality of nail chucks, means driven from said shaft for operating the nailing means to secure said cleat to the underside of the board, said board stop upon again being moved closely adjacent said cleat stop after the board has been moved from its position beyond the cleat stop enabling 55 the nailing of end cleats to the underside of the board with the side edges of the cleats in alignment with the ends of the board and the nailing of side cleats to the underside of the board with the side edges thereof flush with the side edges of the board, and said table having a remote stop for positioning the board so as to 60

receive the cleat spaced from the edges of the board.

53. In a machine for nailing a plurality of cleats to a sheet of board material to form a cleated panel of polygonal shape, in combination, a main shaft, a table having a nailing position, a cleat stop having a work engaging surface for receiving the side edge of a cleat, means including cleat engaging elements driven by said shaft located beneath the board and movable into and out of pressure engagement with the cleat, said cleat stop and cleat engaging elements engaging the cleat from opposite sides and cooperating to hold the cleat rigidly in position during the nailing operation, a movable board stop closely adjacent said cleat stop and having a work engaging surface in vertical alignment with the work engaging surface of said cleat stop, said stops being arranged so that the cleat is beneath the board, said board stop upon being moved away from the cleat stop enabling a board to be slid over said table beyond the cleat stop to enable the nailing of a cleat spaced from the edges of the board, nailing means including a plurality of nail chucks, means driven from said shaft for operating the nailing means to secure said cleat to the underside of the board, said board stop upon again being moved close adjacent said cleat stop after the board has been moved from its position beyond the cleat stop enabling the nailing of end cleats to the underside of the board with the side edges of the cleats in alignment with the ends of the board and the nailing of side cleats to the underside of the board with the side edges thereof flush with the side edges of the board, and said table having a remote stop for positioning the board so as to receive the cleat spaced from the edges of the board, said remote stop being pivoted and having a surface so constructed and arranged that the board may cam the stop aside to enable the board to be slid beyond said remote stop when desired.

54. In a machine for nailing a plurality of cleats to a sheet of board material to form a cleated panel of polygonal shape, in combination, a main shaft, a table having a nailing position, a cleat stop having a work engaging surface for receiving the side edge of a cleat, means including cleat engaging elements driven by said shaft located beneath the board and movable into and out of pressure engagement with the cleat, said cleat stop and cleat engaging elements engaging the cleat from opposite sides and cooperating to hold the cleat rigidly in position during the nailing operation, a movable board stop closely adjacent said cleat stop and having a work engaging surface in vertical alignment with the work engaging surface of said cleat stop, said stops being arranged so that the cleat is beneath the board, said board stop upon being moved away from the cleat stop enabling a board to be slid over said table beyond the cleat stop to enable the nailing of a cleat spaced from the edges of the board, nailing means including a plurality of nail chucks, means driven from said shaft for operating the nailing means to secure said cleat to the underside of the board, said board stop upon again being moved closely adjacent said cleat stop after the board has been moved from its position beyond the cleat stop enabling the nailing of end cleats to the underside of the board with the side edges of the cleats in alignment with the ends of the board and the nailing of side cleats to the underside of the board with the side edges thereof flush with the side edges of the board, and said table having a remote stop for positioning the board so as to receive the cleat spaced from the edges of the board, said remote stop being pivoted and having a surface so constructed and arranged that the board may cam the stop aside to enable the board to be slid beyond said remote stop when desired.

edges of the board, and means in connection with said cleat engaging elements for preventing the pressure of said cleat engaging elements from becoming excessive when wide cleats are to be nailed.

55. In a machine for nailing a plurality of cleats to a sheet of board material to form a cleated panel of polygonal shape, in combination, a main shaft, a table having a nailing position, a cleat stop having a work engaging surface for receiving the side edge of a cleat, means including cleat engaging elements driven by said shaft located beneath the board and movable into and out of pressure engagement with the cleat, said cleat stop and cleat engaging elements engaging the cleat from opposite sides and cooperating to hold the cleat rigidly in position during the nailing operation, a movable board stop closely adjacent said cleat stop and having a work engaging surface in vertical alignment with the work engaging surface of said cleat stop, said stops being arranged so that the cleat is beneath the board, said board stop upon being moved away from the cleat stop enabling a board to be slid over said table beyond the cleat stop to enable the nailing of a cleat spaced from the edges of the board, nailing means including a plurality of nail chucks, means driven from said shaft for operating the nailing means to secure said cleat to the underside of the board, said board stop upon again being moved closely adjacent said cleat stop after the board has been moved from its position beyond the cleat stop enabling the nailing of end cleats to the underside of the board with the side edges of the cleats in alignment with the ends of the board and the nailing of side cleats to the underside of the board with the side edges thereof flush with the side edges of the board, means in connection with said cleat engaging elements for preventing the pressure of said cleat engaging elements from becoming excessive with an increase in the width of the cleats to be nailed, and means whereby the nail chucks may be staggered during the nailing of a complete set of cleats to the board without the interrupting of normal operation of the machine.

56. In a machine for nailing a plurality of cleats to a sheet of board material to form a cleated panel of polygonal shape, in combination, a main shaft, a table having a nailing position, a cleat stop having a work engaging surface for receiving the side edge of a cleat, means including cleat engaging elements driven by said shaft located beneath the board and movable into and out of pressure engagement with the cleat, said cleat stop and cleat engaging elements engaging the cleat from opposite sides and cooperating to hold the cleat rigidly in position during the nailing operation, a movable board stop closely adjacent said cleat stop and having a work engaging surface in vertical alignment with the work engaging surface of said cleat stop, said stops being arranged so that the cleat is beneath the board, said board stop upon being moved away from the cleat stop enabling a board to be slid over said table beyond the cleat stop to enable the nailing of a cleat spaced from the edges of the board, nailing means including a plurality of nail chucks, means driven from said shaft for operating the nailing means to secure said cleat to the underside of the board, said board stop upon again being moved closely adjacent said cleat stop after the board has been moved from its position beyond the cleat stop enabling the nailing of end cleats to the underside of the board with the side edges of the cleats in alignment with the ends of the board and the nailing of side cleats to the underside of the board with the side edges thereof flush with the side edges of the board, and means in connection with said cleat engaging elements for preventing the pressure of said cleat engaging elements from becoming excessive with an increase in the width of the cleats to be nailed, and means whereby the nail chucks may be staggered during the nailing of a complete set of cleats to the board without the interrupting of normal operation of the machine.

with the side edges of the cleats in alignment with the ends of the board and the nailing of side cleats to the underside of the board with the side edges thereof flush with the side edges of the board, and means including guides at the side of the machine for spacing the ends of certain cleats from the adjacent edges of the board.

57. In a machine for nailing a plurality of cleats to a sheet of board material to form a cleated panel of polygonal shape, in combination, a main shaft, a table having a nailing position, a cleat stop having a work engaging surface for receiving the side edges of a cleat, means including cleat engaging elements driven by said shaft located beneath the board and movable into and out of pressure engagement with the cleat, said cleat stop and cleat engaging elements engaging the cleat from opposite sides and cooperating to hold the cleat rigidly in position during the nailing operation, a movable board stop closely adjacent said cleat stop and having a work engaging surface in vertical alignment with the work engaging surface of said cleat stop, said stops being arranged so that the cleat is beneath the board, said board stop upon being moved away from the cleat stop enabling a board to be slid over said table beyond the cleat stop to enable the nailing of a cleat spaced from the edges of the board, nailing means including a plurality of nail chucks and a driving head, means driven from said shaft for operating the nailing means to secure said cleat to the underside of the board, said board stop upon again being moved closely adjacent said cleat stop after the board has been moved from its position beyond the cleat stop enabling the nailing of end cleats to the underside of the board with the side edges of the cleats in alignment with the ends of the board and the nailing of side cleats to the underside of the board with the side edges thereof flush with the side edges of the board, and means for compensating for the difference in resistance to the driving action of said head when less than a full complement of nail ends are being driven so that the nails are driven with their heads flush with the board surface both when a full complement of nails are being driven and when a lesser number are being driven.

58. In a machine for nailing a plurality of cleats to a sheet of board material to form a cleated panel of polygonal shape, in combination, a main shaft, a table having a nailing position, a cleat stop having a work engaging surface for receiving the side edges of a cleat, means including cleat engaging elements driven by said shaft located beneath the board and movable into and out of pressure engagement with the cleat, said cleat stop and cleat engaging elements engaging the cleat from opposite sides and cooperating to hold the cleat rigidly in position during the nailing operation, a movable board stop closely adjacent said cleat stop and having a work engaging surface in vertical alignment with the work engaging surface of said cleat stop, said stops being arranged so that the cleat is beneath the board, said board stop upon being moved away from the cleat stop enabling a board to be slid over said table beyond the cleat stop to enable the nailing of a cleat spaced from the edges of the board, nailing means including a plurality of nail chucks and a driving head, means driven from said shaft for operating the nailing means to secure said cleat to the underside of the board, said board stop upon again being moved closely adjacent said cleat stop after the board has been moved from its position beyond the cleat stop enabling the nailing of end cleats to the underside of the board with the side edges of the cleats in alignment with the ends of the board and the nailing of side cleats to the underside of the board with the side edges thereof flush with the side edges of the board, and means for compensating for the difference in resistance to the driving action of said head when less than a full complement of nail ends are being driven so that the nails are driven with their heads flush with the board surface both when a full complement of nails are being driven and when a lesser number are being driven, said means comprising means for raising and lowering the nail driver engaging surface of the driving head.

EARLE V. PATTERSON.

SUSAN R. MACY,

*Executrix of the Estate of Clarence A. Macy,
Deceased.*

CERTIFICATE OF CORRECTION.

Patent No. 2,188,117.

January 23, 1940.

EARLE V. PATTERSON, ET AL.

It is hereby certified that error appears in the printed specification of the above numbered patent requiring correction as follows: Page 14, second column, line 41, claim 7, before the word "rotation" insert the; page 15, first column, line 16, claim 11, for "successive" read excessive; line 29, claim 12, for "effctive" read effective; page 18, second column, line 9, claim 44, for "working" read work; page 19, first column, line 54, claim 50, after the comma and before "stops" insert said; and that the said Letters Patent should be read with this correction therein that the same may conform to the record of the case in the Patent Office.

Signed and sealed this 5th day of March, A. D. 1940.

(Seal)

Henry Van Arsdale,
Acting Commissioner of Patents.
